CARD PUNCHING MACHINE

Clair D. Lake, Binghamton, and Francis E. Hamilton, Endicott, N. Y., assignors to International Business Machines Corporation, New York, N. Y., a corporation of New York

Application December 3, 1943, Serial No. 512,690

35 Claims. (Cl. 164—113)

This invention relates to record punching machines and more particularly to the type in which digit storage devices, either mechanical or electrical in form, are set up by the operator, after which they are utilized to control a record punching machine, preferably of the successive actuation type.

A broad object of the present invention is to enable a selective coordination between the column punching selecting means and the digit storage devices so that different patterns of cards can be punched and to further improve the system, so that for each form of pattern card punching operations will be automatically effected and in an efficient manner without consuming time of the operator that could be employed for keying operations.

A further object of the invention is to coordinate a keyboard, on which fixed data may be set up, with a punching machine so that such data may commonly be punched on a series of cards. Likewise, consistent with the preceding object, selective connections are interposed between the keyboard and the column selecting means of the punching machine so that the columns of the record receiving the fixed data may be selected at will.

Another object of the invention is to allocate a predetermined maximum number of storage columns for setting up digits of amounts of large denominations and to provide a selective arrangement whereby all of the storage columns may be utilized for storage of amounts of large denominations, or certain storage columns may be skipped, so that the operator need only be concerned with the setting up of the necessary storage columns. This feature of the invention still further improves the efficiency of the system and renders it more flexible than heretofore, because in some instances it enables the setting up of storage devices of representations of large amounts and then, when the requirements change, fewer storage columns need only be set up.

A still further object of the present invention is to provide an arrangement which even eliminates the necessity of setting up some of the storage columns which would ordinarily be set up to represent zeros to complete digit setting of the remaining storage columns.

This still further reduction in time occupied by the operator in setting up the remaining storage columns further increases the efficiency of the system and the incorporation of this feature 55

also results in a saving of punching time by the punching machine as will now be explained.

In the present system where an amount of say \$5.00 is to be set up and considerably more storage columns are provided to normally enable setting up of digits of a much higher denomination, it is only necessary for the operator to depress the keys representing the digits 500 which are set up successively in the storage columns to represent this amount. Before setting up such digits the operator in the improved machine depresses a special key which causes the storage of one or more X representations in some of the storage columns. In the present machine, punching of the card columns is effected in an inverted manner and to further understand this it is well known that it is common practice to punch a field so that the card column at the extreme right receive the digit of units denomination whereas the card column at the extreme left receive the digit of the highest denomination. Contrasting with this practice, the present machine, through the selective plug connections enables the column selecting means of the punching machine and the storage columns to be interconnected for control in an inverted manner so that the card column at the extreme left of a field receives the digit of the units denomination; the next column to the right the digit of the tens denomination, etc. Hence, with such novel interconnections in the present machine for a capacity of five storage columns the card field will be punched as 005XX, the X punching being derived from the X representing storage column. The reading out of the first X representation from the related storage column will cause the carriage skipping mechanism of the punching machine to be operative after 005 is punched and the card carriage will be skipped from the related column position to the first column of the next field, or to the last column position in the present machine. The variable position of the X storage receiving column enables the card carriage to be skipped from any card column position, thus saving considerable time in punching operations.

It is, therefore, a broad object of the invention to provide means under control of an operator to set up in a storage column an X representation which is subsequently read out to cause carriage skipping operations.

As a result of the possibility of selective and variable interconnections between the storage columns and the column selecting means of the punching machine, an alternative arrangement

enables the card columns to be punched in a manner different from that just described. The storage columns are set up successively in the same manner to represent the amount 500 but by different interconnections the storage columns may control the column selecting means of the punching machine so that the related field will be punched in the same sequence that the digits are set up. Thus, in the modification in setting up the digits 500 in the storage columns the card field is punched to represent 500 as before but with the digit "5" of the highest denominational order always appearing in the card column at the extreme left of the card field, the digit of the next lower denomination in the next column at the right and so on. Upon terminating key strokes for digit setup of the storage columns for the amount to be punched, the operator then depresses a special key which causes $\mathbb{X}$ storage in the next storage column, which, upon being read out, causes the punching at the $\mathbb{X}$ index point and the skipping of the card carriage from the card column position following that column receiving the punching of the units digit.

Therefore, another object of the invention is to provide means to cause not only the skipping of the card carriage when the storage column representing $\mathbb{X}$ is read out, but to also cause the perforation at the $\mathbb{X}$ index point position of the related card column. The variable location of this $\mathbb{X}$ perforation in cards passing through an accounting machine may be utilized as a control for the purpose of effecting a variable column shift so that the amount read from the card field may be shifted to the proper column positions of an accumulator or printing orders of a printing mechanism.

The use of the above features singly and the coordination of the above described features in combination has greatly augmented the efficiency of punching systems heretofore employed and in practice has enabled continuous keying operations by the operator without consuming time of the latter due to the time required for completing incidental operations in the punching machine. The reduction of the number of keying strokes made by the operator by requiring the operator to set up only the digits of the amount without the "0" key strokes for completing a field and the possibility of selectively changing at will the number of card columns comprising a field has increased the overall efficiency of the former system.

Other objects of the invention will be pointed out in the following description and claims and illustrated in the accompanying drawings, which disclose, by way of example, the principle of the invention and the best mode, which has been contemplated, of applying that principle.

In the drawings:

Fig. 12 is a perspective view showing the assembly of the keyboards and punching machine comprising the present system.

General description

The punching system to be described more in detail hereinafter consists of a ten key keyboard, 30 and a card punching machine of the successively actuated type which is controlled by a digit storage unit, all of which units are so co-ordinated as to enable continuous keying operations by an operator without consuming time of the operator by requiring unnecessary key strokes and while card ejection and card feeding operations of the punching machine ensue. A multiple column keyboard shown herein as having a capacity of seven card columns is provided and in accordance with the keyboard setting, the digit information represented thereby is punched by the punching machine to provide common data for a plurality of cards. In the punching system outlined herein the variable information to be punched on cards is visibly read by the operator from checks and in accordance with the data printed or written on the checks the operator makes the desired ten key keyboard operations. Incidentally, the storage unit is controlled by a ten key keyboard whereas the fixed data for punching a plurality of cards is derived from the multiple column keyboard, which keys when once depressed remain depressed for a series of continuous punching operations.

The storage unit is of the electrical relay type and has a maximum capacity of fifteen digit storing columns. The digit setup of the storage units is effected progressively as the keys of the ten key keyboard are successively operated. To speed up the operations of the machine and to enable overlap the punching machine is initiated in operation to punch a field immediately upon completion of the digit setup in the related storage columns. This makes the storage columns of the storage unit as they are cleared out available for further digit storage operations and available before the punching machine has completely punched an entire card. Overlapping operations effected in a manner to be described more in detail hereinafter greatly reduce the waiting time of the operator if not completely eliminating it, enabling the operator to give his or her entire attention to the keying op-

erations of the ten key keyboard in accordance with the data read from the checks.

The utility of the present punching system is augmented by making it possible by a rearrangement of circuits to punch either two different card forms outlined in Figs. 5 and 6. The card form shown in Fig. 5 is that required for punched card accounting systems for the New York and Boston Federal Reserve Banks, while the other card form shown in Fig. 6 is that which has been found desirable for the punched card accounting systems of the Chicago Federal Reserve Bank. In the subsequent description, the card form shown in Fig. 5 will be known as the "New York" form and the other in Fig. 6 as the "Chicago" form.

From Fig. 5 it will be observed that the New York form consists of twenty columns of punching, six columns being punched under control of the multiple column keyboard and fifteen columns under control of the storage columns. It will be observed that column 6 receives a double punching in that column; one punching under control of the related storage column of the storage unit and the other punching under control of a bank of keys of the multiple column keyboard.

More specifically, in the New York card form the first two columns are punched under control of the related storage columns to represent the number of the State in which the paying bank is located. Columns 3-6 are punched to represent what is known as the "ABA" number of the paying bank and this data is punched under control of the related storage columns. Contrasting with the usual procedure of reading out the digits in the storage columns in the order the digits are set up, in the present arrangement the storage devices are read out in reverse order to accomplish punching of the digits beginning with the units order. That is, the units, tens, hundreds and thousandths digits are punched in columns 3-6 successively. This method, or arrangement of punching, facilitates sorting operations effected under control of such columns of the card. Columns 6-11 of the New York card form are punched under control of the multiple column keyboard and represent the "ABA" number and state number of the sending bank.

Columns 12-20 are allocated for the digit punching of the amount on the check and such digit punching is effected in the reverse denominational order. The units digit of the number appears in column 12 and the highest denominational digit appears in column 20 with other digits in between such columns. In this case, however, the reverse denominational order of digit punching has been adopted because it permits a saving of punching time and time of the operation of the punching machine by making it possible to skip over higher numbered columns of the card which are not punched because the amount of the check is small.

Due to the relatively large size of the check amount field on the New York form, it will be necessary for the operator to punch a great many superfluous zeros to the left of the significant figures to fill out the field unless some special time saving devices were employed, since a very large majority of checks are relatively small denominations.

Provision has been made in this machine, therefore, to normally limit the storage columns to the storage of five columns of amounts when

punching according to the New York card form, making it unnecessary for the operator to punch the first four zeros in cases where the amount on the check consists of five figures or less.

When, for example, a check of an amount of \$5.00 is to be punched and which amount, denominational speaking, is small compared to the maximum denominational capacity of nine columns of the amount field, the storage columns 10 are delimited to five storage columns 11, 12, 13, 14 and 15, and storage columns 7, 8, 9 and 10 are skipped. The "0" key is depressed to set up X representations in storage columns 11, 12 and then the digit keys are successively depressed to set up 500 in storage columns 13, 14 and 15, respectively. The storage columns are read out reversely to punch card columns 12, 13 and 14 to represent 005 under control of storage columns 15, 14, 13, respectively. When the X representation of storage column 12 is read out by the column selector in the punching machine effected when the carriage is in position to punch card column 15 (see Fig. 5) this "X" readout will set in operation a skip mechanism which will skip the card carriage from the column 15 position to the last card column position and then eject the card. This enables a great saving in time of operation of the punching machine. In other instances where the check amount is \$1,000, or more, the operator may first depress the X key on the ten key keyboard which expands the storage columns to its full capacity of nine columns of amount.

The Chicago card form shown in Fig. 6 in 35 card fields is arranged in a slightly different manner from the New York card form and consists of thirteen card columns but the same basic data is punched on the card. The Chicago card form consists of column 1 which is punched under control of the keyboard to represent the number of the State of the paying bank. Columns 2-5 are punched to represent the "ABA" number of the paying bank and are punched under control of the related storage columns. 40 As in the case of the New York card form, reverse punching ensues for columns 2, 3, 4 and 5. Columns 5-7 of the Chicago form are punched under control of the multiple column keyboard to represent the batch number which remains constant for a series of cards. It will be observed that column 5 receives a double punching; one under control of the related storage column and the other under control of the multiple column keyboard. Finally, columns 8 to 13 are used for 55 the allocation of the digit punching of the amount of the check. On the Chicago form the check amount field consists of only six columns and no skipping circuit has been provided to eliminate part of the storage columns.

60 However, since the amounts on the checks are usually small, provision has been made for a different method of punching the amount of the check for the Chicago card form, but this is applicable for the New York card form as well by changing the plug interconnection between storage columns and the column selector. Instead of punching the check amounts in reverse denominational order as described for the New York card form and still provide an X skipping over the remaining columns, it is possible to utilize another procedure in which the check amounts are punched in normal denominational order beginning with the left hand column of the amount field. Thus, in setting up the storage columns

for an amount of \$5.00, the operator will merely depress the keys of the ten key keyboard for the number 500 to set this number in the storage columns and then depress the manual bar to signify completion of the operation which will also set up an X representation. This amount 500 would be then punched in direct order on the card as 500 in columns 12, 13, 14 for New York form and columns 8, 9, 10 for Chicago form and a perforation would be punched in the X index point position of the column following the last of the above mentioned zeros. With this X perforation in column 15 of the New York form, or column 11 of the Chicago form, it can then be utilized as a control in a conventional tabulating machine to control shifting circuits to shift the 500 to the right a sufficient number of places to bring the digits of the number into the corresponding orders of the accumulator or type bars. This method of punching the amount will be referred to in a later discussion as "zero elimination."

The sensing of the X representation will, as before, cause the carriage skipping mechanism to be operative at different column positions to skip over the higher numbered card columns at the left of digit punching of the amount field.

Keyboard

Mounted on the keyboard (Figs. 3 and 4) is a series of ten digit keys 117N, an error key 117E, a special key 117X and a manual bar 118. Depression of any of the numeral keys 117N will rock a bell crank 119 which, through a pin and slot connection, will move a slider 120 toward the left as viewed in Fig. 3. Each of the sliders cooperates at its left end with a bail 121 to rock the same counterclockwise and the bail in turn will rock a lever 122 to close a pair of contacts 123. Contacts 123 are the bail contacts and are common to the numeral keys 117N and are closed upon the depression of any of said keys.

Individual contacts 124 of which there is one for each key 117N are also closed by the depression of a key. For each slider there is also a lever 125 which is rocked to close the associated pair of contacts 124.

The special key 117X operates a similar slider 120 and lever 125 to close a pair of contacts 124X shown in Fig. 1a. Also for the key 117E there is a separate slider and lever 125 which will close a pair of contacts 124-E (Fig. 1a). The manual bar 118 when depressed also like key 117E closes a pair of contacts not shown in Fig. 3 but designated in Fig. 1a as contacts 130. Neither of the keys 117X, 117E or the manual bar 118 closes the bail contacts 123. These keys and their contacts are mechanically independent of the remainder of the mechanism and being mounted in a separate keyboard K (Fig. 12) may be located in relation to the remainder of the apparatus for convenient manual operation.

In starting, the first key depression causes a circuit to be closed from the current supply line 105, through the bail contacts 123 (Fig. 1a), through F1-2, F2-2 contacts, wire 106, through relay contacts TR1 (Fig. 1j) now in the position shown, C2-9 contacts, relay coil C1, to ground. Accordingly, relay contacts C1-16 close to provide a stick circuit back to the line 105 through relay contacts F2-2 and F1-2 and bail contacts 123 (Fig. 1a). Relay C1 (Fig. 1j) opens contacts C1-9 and closes contacts C1-10. The closure of the latter closes a circuit from wire 106 through contacts C1-10 to relay coil TR to 75

ground. Relay coil TR shifts its contacts TR1 but since contacts C1-9 are open the circuit to the C2 relay coil is open and the latter is not energized during this first key depression, whereas relay coil TR is and remains energized by reason of its stick contacts TR4, which stick circuit extends through contacts TR4, TD1, R3-1, ER1, and wire 107 back to line 105. Hence, when the bail contacts open upon the release of the pressure on the depressed key, relay C1 deenergizes but relay TR remains energized. Upon the next key depression, the circuit extends from the line 105 through relay contacts TR1 now shifted (Fig. 1j), C1-9 now closed, to grounded relay coil C2, the stick contacts C2-16 providing a stick circuit back to line 105 through F1-2, F2-2 contacts, and bail contacts 123. Relay coil C2 closes its contacts C2-10 to energize grounded relay coil TD which opens its contacts TD1 to break the stick circuit of the relay coil TR, which deenergizes. The return of relay contacts TR1 to normal does not cause relay coil C1 to energize because of the opening of relay contacts C2-9. It is thus seen that on odd key depressions relay coil C1 energizes while upon all even key depressions relay coil C2 is energized. As will be later explained, relays C1 and C2 have supplemental contacts in alternate storage columns with supplemental contacts of C1 in all odd storage columns and with supplemental contacts of C2 in all even storage columns. Thus, upon the first key depression closure of C1-1 contacts (Fig. 1b) provides an impulse circuit to storage column 1.

The individual contacts 124 are closed by the respective numeral keys 117N and a circuit is extended from line 105 through F1-2, F2-2 contacts, to the contacts 124 of the 5, 6, 7, 8, 9 and 0 digit keys, whereas upon the depression of one of the digit keys 1, 2, 3, and 4 the circuit extends from the bail contact 123 through the COM1 contacts now closed, F1-3 and F2-3 contacts, to contacts 124 of the digit keys 1-4. When the bail contacts 123 close, a circuit is closed from such contacts to the grounded COM relay coil which closes the contacts COM1 to extend the impulsive circuit to the 124 contacts related to digit keys 1-4. From the other side of the contacts 124 closed by the digit keys 1-9 there are respective wire connections to grounded relay coils K1-K9, one relay for each key, so that depression of a key will energize its respective K relay and close respective "1" and "2" contacts if such relay coil is provided with such contacts. For example, the digit keys designated 1, 2, 3 and 4 upon the closure of their respective contacts, energize only their related relays K1-K4. However, for the 5-9 digit keys which energize their related K5-K9 relays, the latter also close additional "1" and "2" contacts so as to cause in addition the selective energization of the relays K1-K4. Such circuit arrangement provides for the energization of the K relays singly or in combination according to the following code:

Key	Relay
1.....	K1
2.....	K2
3.....	K3
4.....	K4
5.....	K5, K1-K2
6.....	K6, K1-K3
7.....	K7, K2-K3
8.....	K8, K2-K4
9.....	K9, K3-K4
0.....	K10, also K1, K4 for "X" representation

As for the zero digit key, it will be observed that when its contacts 124 are closed the circuit is extended from the contacts 124, by wire 116, thence through ZE7 contacts KE1 contacts, KB1 contacts now closed, to the pickup coil of the K10 relay. The pickup coil of K10 closes contacts K10-1 and K10-2 to select K1 and K4 relays for energization. It should also be observed that the depression of the zero digit key also closes bail contacts 123 to energize C1 or C2, depending upon whether the key depression is an odd or even numbered key depression.

It will be noted that to illustrate the present invention, fifteen storage columns are shown and in punching a card for the New York form, fifteen storage columns may be utilized, whereas for punching the Chicago card form the maximum number of ten storage columns may be utilized. It will be observed then in each depression of the digit key "1," K1 closes its contacts in each storage column, closing K1-1 for column 1 to K1-15 for column 15. The same is true for the other K2, K3, K4 relays so that for each key depression, contacts will be closed in all of the fifteen storage columns upon each key depression. It will be seen that for column 1 relays 11, 12, 13 and 14 are selected for energization by closure of respective contacts K1-1, K2-1, K3-1 and K4-1. Similar relays are provided for each column of the storage unit, relay coils 21-24 for column 2 being provided. The tens (and hundreds) digit is provided to indicate the column number and the units digit to indicate the relay number. Hence, 52 indicates relay 2 in column 5; 114 represents relay 4 of column 11, etc. Therefore, closure of K1 relay contacts in the storage columns energizes relays 1-4 singly or in combination but only in the storage columns selected for operation are such contacts effective for digit setup.

Upon the first key depression, contacts C1-1 are closed and energizing circuits for relays 1-4 of storage column 1 are provided from line 105, through bail contacts 123 (Fig. 1a), COM2 contacts now closed, wire 110, CB1 contacts (Fig. 1b), thence serially through C1-1 contacts, PE1 contacts, R3-3 relay contacts, P1-1 relay contacts now in the position shown, B2 contacts to the particular K1-K4 contacts now closed, to the respective 11-14 relay coils for storage column 1, to ground.

Having been energized, the relay coils 1-4 are held energized as follows: It will be noted that the relays 1-4 in each column and others are of the double type consisting of a pickup coil P and a hold coil H with the h contacts adjacent the H winding being the conventional stick or hold contacts which are closed when the pickup winding is energized. The stick circuit for relays 11-14 extends from ground through the stick h contacts, wire 111, through DO1-1 contacts (Fig. 1c), back to line 105. In the impulsive circuit for picking up relay coils 11-14, it will be recalled that the circuit also extended through normally open CB1 (Fig. 1b) contacts and such contacts are closed because when the COM2 contacts (Fig. 1a) close an impulse is directed to the grounded CB relay coil to energize the latter and close CB1-1 contacts.

It will be noted that the impulsive circuit for energizing 11-14 relay coils also extends to the grounded pickup relay coil A when digit storage is effected for column 1, which coil energizes concurrently with the energization of the selected 11-14 relays and its pickup winding closes its h contacts to pick up the hold coil H of the A re-

lay coil. The stick circuit for the hold coil H of relay A is the same as for 11-14 relays. Relay coil A closes its contacts A1 which prepares storage column 2 of the storage circuit for entry of a storage impulse upon the second key depression, the impulse now being directed from K1-2, K4-2 contacts to energize relay coils 21-24. It will be noted that the stick circuit for those relays as well as the B column relay also extends back by wire 111 to line 105 through DO1-1 contacts.

The digit impulse on the first key depression cannot be transmitted to relays 21-24 of the second storage column even though K1-2 to K4-2 contacts and relay contacts A1 are closed because C2-1 contacts are open. However, on the second key depression, relay coil C2 energizes to close contacts C2-1 and storage column 2 will be set up and in this case relay coil B energizes to open contacts B2 of the storage column 1 to prevent setting up of such column on a subsequent odd key depression and closes B1 contacts in storage column 3, preparing it to receive the third digit setup. Relay coil C energizes for the digit setup in storage column 3, opening C2 contacts to prevent a setup in storage column 2 and closing contacts C1 preparatory for a digit setup in storage column 4. In the same manner, digit setup successively ensues for as many storage columns as are set up.

Punching card—Chicago card form—complete punching of amount field

From Fig. 6 it will be observed that ten card columns of the Chicago form of card are appropriated for punching under control of storage columns 1 to 10 which are set up in serial order.

It will be observed that card columns 2, 3, 4 and 5 of the card are punched under control of storage columns 4, 3, 2 and 1, respectively to represent the ABA number of the paying bank. The amount of the check is punched in card columns 8, 9, 10, 11, 12 and 13, inclusive and punching is effected under control of storage columns 10, 9, 8, 7, 6, 5, respectively. Hence, it is apparent that storage columns 5 to 10 are allocated for setting up of the digits in the amount and immediately upon setting up of the last digit of the ABA number in storage column 4, the next depression of the key will cause an impulse to be directed to storage column 5 (Fig. 1b), the impulse being directed from the CB1 contacts, impulse line 108, through C1-3 and D1 contacts both of which are now closed, to the F2 contacts, through K1-5 to K4-5 contacts to set up the 51-54 relays of storage column 5. With the appropriate relays being closed, storage column 6 is then set up upon the next key depression.

This digit impulse is directed by wire 108 through C2-3 and E1 contacts now closed (Fig. 1c) G2 contacts, K3 contacts now closed, through K1-6 to K4-6 contacts to selectively energize the 61-64 relays.

For setting up storage column 7 by the next depression of the key the impulse circuit is slightly different and from Fig. 1c, it will be observed that it extends from impulse line 108, through the C1-4 and F1 contacts now closed, thence through the ZE9 contacts now in the position shown, thence through the NY11 contacts now in the position shown, through the H2 contacts to the K1-7 to K4-7 contacts to selectively energize the 71-74 relays for storage column 7. Thereafter, storage column 8 will be set up. However, it will be observed that the impulse circuit for set-

ting up this storage column extends from impulse wire 108, but through the NY10 contacts (Fig. 1b), now closed, wire 109, thence through C2-4 contacts now closed (Fig. 1c), G1 contacts now closed, I2 contacts now closed, to selectively energize the 81-84 relays, depending upon the K1-K4 contacts closed for storage column 8. Thereafter, successive key depressions will be transmitted by the impulse wire 109 to set up storage columns 9 and 10 for the next two key depressions.

Of course, if the denominational amount of the check is not equal to the six card columns, it is necessary for the operator to first depress the zero key one or more times, then followed by the depression of keys representing significant digits comprising the amount of the check. This is the manner of setting up the storage columns representing the amount of the check in the event that time saving devices to be subsequently described are not utilized.

From Fig. 1b it is evident that the holding circuit for relays 11-14 for storage column 1, 21-24 for column 2, 31-34 for column 3 and 41-44 for column 4 as well as the column relays A, B, C, and D is controlled by the DO1 contacts. On the other hand, the corresponding relays for storage columns 5-10 extend by a wire 104 (Fig. 1c) through NY12 contacts now in the position shown, thence through the DO2-4 contacts back to line 105. This splitup of the holding circuits sub-divides the storage columns into two independent units and as will be clearer later on it enables punching to be effected under control of the storage columns representing the ABA number while the operator is busy setting up the storage columns 5-10 to represent the amount of the check.

Signals—Punching card according to Chicago form

Since there is no visible indication of the digits set up in the storage columns to represent the ABA number and the amount of the check, it is desirable to provide separate signals to indicate the completion of setting up of the storage columns to represent the ABA number and the amount of the check. To this end the lamp L1 (Figs. 1c and 12) is lighted when the setting up of storage column 4 has been completed, and in this instance relay D will be energized to close the D5 contacts (Fig. 1c) closing a circuit from the line 105, through DO1-3 contacts, D5 contacts, NY9 contacts, through lamp L1 to ground. This lamp remains lighted until punching has been completed under control of storage column 4 at which time, as will be subsequently explained, the DO1 relay is energized to open the DO1-3 contacts and extinguish L1 lamp. The other lamp L2 (Figs. 12 and 1c) is lighted when the manual bar is depressed after setting up of the desired number of storage columns 5-10 to represent the amount of the check. Suffice to say at this time when the manual bar is depressed it will energize P2 relay to transfer P2-3 contacts (Fig. 1c), closing a circuit from line 105, wire 107, through P2-3 contacts now transferred, wire 102 (Fig. 1c), through the L2 lamp to ground. Lamp No. 2 remains illuminated until punching has been effected under control of the storage columns representing the amount of the check.

Setting up X representation in storage columns for subsequent carriage skipping operations

A time saving procedure adaptable for the present punching system enables an X setup for

each of the storage columns preceding the significant digit of the highest denominational order, it being recalled that the amounts are punched in the amount representing field beginning with the column at the extreme left of the amount field and in the reverse denominational order although the digits of the amount are set up in the storage columns in succession, beginning with the digit of the highest denominational order, etc. The means used for skipping the card carriage consists of storing X coded representations in one or more of the storage columns which precede the significant digit of the highest denominational order. This will be made clear 5 when it is understood that for the Chicago card form the amount representing field consists of six card columns and in setting up the amount \$5.00, storage columns 5, 6, and 7 are set up to represent X coded representations; then columns 8, 10 9, and 10 would be set up to represent the digits 500 as keys are depressed in this order. However, when such storage columns control the punching machine, punching is effected successively in reverse denominational order and if all 15 columns were punched it would be represented in card columns 8, 9, 10, 11, 12, and 13 as 005XXX. However, the storage column having the first setting up of the X representation, or storage column 7 in the assumed example, is the instrumentality for causing the skipping of the card carriage after reading out the X representation in storage column 7, thus eliminating punching of card columns 12, 13 and saving some time in punching operations. The circuits whereby such 20 X representations may be set up in one or more storage columns will now be described.

When the storage column 4 is set up to represent the thousands digit of the ABA number, relay D is energized and is maintained energized so 40 that its contacts D4 (Fig. 1a) will be kept closed. It will also be recalled that when a key is depressed the CB relay is energized to thus transfer its CB2 contacts and upon release of the pressure of the key for effecting storage of the digit in storage column 4 the CB relay will be deenergized and the CB2 contacts will transfer back to the normal position shown in Fig. 1a, thus closing a circuit from the line 105 through DO2-2 contacts, CB2 contacts now in normal position, NY1 contacts, D4 contacts now closed, to the grounded pickup coil of the KB relay. The pickup coil of the KB relay will close the h or stick contacts and the grounded hold coil of the KB relay will be maintained energized through the h contacts, wire 131, and DO2-2 contacts back to line 105. Summarizing, upon the depression of the key for effecting digit storage in column 4, the KB relay is energized to thereby close its KB1 contacts 45 which are in the energizing circuit of the pickup coil of the K10 relay. If the operator finds that the digits of the amount to be punched in the amount representing field are less than six digits, the zero key is depressed one or more times, the number of times being the difference between the number of digits of the amount of the check and six. For setting up the amount of \$5.00, the operator will immediately recognize that the zero key is to be depressed three times before depression of the "5" digit key. Upon the first depression of the zero digit key a circuit is closed from the line 105 through bail contacts 123 (Fig. 1a), through contacts F1-2 and F2-2, through the 124 contacts pertaining to the zero digit key, thence by a wire 116 to contacts ZE7 now closed. 50 55 60 65 70 75

Punch initiation—Chicago card form

thence through KE1 contacts now closed, through KB1 contacts which have previously closed, to the grounded pickup coil of the K10 relay. The K10 relay thereupon closes its contacts K10-1 and K10-2 which will pick up the K1 and K4 relays for energization. The latter will close their respective contacts in storage column 5, thereby causing energization of relays 51 and 54. Relays 1 and 4 in any storage column are the relays which are to be set up to represent in code the X character. As will be evident later on the energization of such relays in combination will select the X punch control magnet of the punching machine to perforate at the X index point position of the correlated card column and to cause the energization of a skip control magnet.

A repetition of the operation of the zero key then ensues until the storage column is reached in which the first significant digit is to be set up and in the present example this consists of storage column 8. When any digit key is now depressed, one or more of the relay contacts K1-16, K2-16, K3-16 and K4-16 (Fig. 1a) will close without a concurrent opening of contacts K10-3. When the first digit key 5 is depressed, a circuit will be closed from line 105, through DO2-2 contacts, CB2 contacts now transferred, wire 132, through K10-3 contacts now closed, KB2 contacts now closed, through one or more of the "16" contacts of the K1-K4 relays, grounded pickup coil of the KE relay. The pickup coil of the KE relay will close its h contacts and the grounded hold winding of the KE relay will be held energized through such contacts, wire 112 (Fig. 1a), through the DO2-2 contacts, to the line 105. Energization of the KE relay will open the KE1 contacts (Fig. 1a), and the opening of such contacts prevents the energization of the K10 relay in the event that the zero key is depressed for setting up zeros in the storage columns of lower orders. For example, in setting up the amount \$5.00, the zero key is twice depressed after depression of the 5 digit key and the opening of the KE1 contacts prevents the energization of the K10 relay and the operations previously described. Depression of the zero key under such circumstances merely causes a spacing operation of the storage columns.

It will be recalled that the zero digit key also closes the ball contacts 123 and energizes the alternating relays C1 and C2, dependent upon whether the setup is for an odd or even storage column. Taking the present example into consideration, when storage column 8 is set up to represent the digit 5, it will cause the energization of the H column relay (Fig. 1c) and the latter will close its H1 contacts so that upon depression of the zero key for storage column 8, the impulse will pass through the C1-5 contacts because this is energized upon setting up an odd number storage column, thence through the H1 contacts now closed, the J2 contacts now closed, and the impulse will be directed to the I column relay for storage column 9, rendering the impulsive circuit for storage column 10 effective by the closure of the J1 contacts (Fig. 1c). Hence, it is obvious in setting up the storage columns to represent zeros to the left of the first significant digit, none of the relays 1-4 of the related storage column is energized. As will be later apparent in such storage columns the circuits are nevertheless so arranged that punching of zeros will be effected.

After digit storage has been completed at given points in the storage circuits, it is desirable that a signal be transmitted to the punching machine to permit the latter to proceed to punch under control of the storage columns which have been completely set up for each field and the multiple keyboard columns. This is done in order that no delay will ensue to the operator, due to the time required for feeding and ejecting cards in the punching machine and is particularly desirable because upon the completion of punching under control of storage columns, such storage columns will be cleared out and rendered available for subsequent digit storage by the operator before the punching machine has completely ejected and fed a new card into punching position.

After the operator has completed digit storage for storage column 4 an impulse is transmitted to the punching machine upon making the fifth key stroke so that punching may ensue under control of storage columns 1-4 and keyboard columns 1, 2, 3 and 4. In setting up the storage columns to represent a card to be punched according to the Chicago form, this signal is transmitted upon making the first key stroke for setting up of the amount of the check and which would consist of the fifth key stroke by the operator. It will be recalled that when storage column 4 is set up column relay D will be energized to close D3 contacts (Fig. 1a). When the fifth key stroke is effected, C1-13 contacts in series with the D3 contacts will also be closed because this is an odd numbered key depression. Thereupon, a circuit will be closed from the line 105, through COM3 contacts now transferred (Fig. 1a), NY6 contacts now in the position shown, C1-13 and D3 contacts now closed, wire 135, PDI contacts, wire 133, to the pickup coil of the grounded P1 relay. The pickup coil of P1 closes the h or stick contacts and a stick circuit of the hold winding of the P1 relay is established through the h contacts, wire 111, and DO1-1 contacts (Fig. 1c) back to the line 105. When the P1 relay energizes, it closes the P1-3 contacts (Fig. 1a) which, as will be described later on, is the instrumentality for transmitting the signal to the punching machine so that punching may be effected to punch card columns 1-7 and then stop unless P2 relay is energized.

When the setting up of the storage columns for representing the amount of the check has been completed, a supplemental signal is transmitted to the punching machine to punch in a reverse denominational order on the card columns the data represented by storage columns 5-10 inclusive. The P2 relay (Fig. 1j) is the instrumentality for transmitting this signal. When storage column 10 has been set up the J column relay is energized to transfer its J4 contacts (Fig. 1j) and after the storage column 10 has been set up the manual bar 118 is depressed to close its contacts 130, thereby closing a circuit from the line 105, wire 107, through contacts 130, wire 134 (Fig. 1a and Fig. 1j), thence through the NY4 contacts now in the position shown, through the J4 contacts now transferred, the ZE2 contacts now in the position shown, thence through contacts F2-5, to the grounded pickup winding of the P2 relay. The pickup winding of the P2 relay will close its h contacts and a stick circuit for the grounded hold winding of the P2 relay extends through the h contacts, wire 131 (Fig. 1j)

and Fig. 1a) through the DO2-2 contacts, back to line 105. The P2 relay closes its P2-2 contacts (Fig. 1a) which, as will be subsequently described, is in a circuit for transmitting a signal to the punching machine so that punching of card columns 8-13 may proceed under control of storage columns 5-10.

Error key operation for clearing out setup storage columns when an error has been detected by the operator and before punching has been initiated under control of the setup storage columns

When the operator becomes aware of an error in the digit setup in one of the storage columns, the storage columns which have been set up may be cleared out by the depression of the error key 117E located on the keyboard. However, such error key depressions should be effected before punch initiation or otherwise as will be described later on; a distinctive signal is given to the operator. Assuming that an error has been located in setting up storage columns 1, 2 or 3 and such storage columns should be cleared out, the operator depresses the error key 117E to thereby close contacts 124E, closing a circuit from the line 105, wire 107 (Fig. 1a) through 124E contacts, wire 136 (Figs. 1a and 1j) to the grounded ER relay. Energization of the ER relay transfers the ER3 contacts (Fig. 1j) to close a circuit from grounded DO1 relay ER3 contacts now transferred, thence through P1-2 contacts, wire 107 (Figs. 1j and 1a) to line 105. The DO1 relay will open its DO1-1 contacts to release all of the energized relays pertaining to storage columns 1, 2 and 3.

Similarly, when an error is located in the storage columns 5-10 which are set up to represent the amount of the check for the Chicago card form, the operator depresses the error key 117E to energize the ER relay which will also close the ER2 contacts (Fig. 1j). A circuit will be closed from ground, through the DO2 relay, through ER2 contacts, P2-3 contacts, wire 107, to line 105. This will clear out all the storage columns which have been set up to represent the digits of the amount of the check.

It is pointed out that in the event that punching has already been initiated under control of the storage columns representing the ABA number, that is, storage columns 1, 2, 3 and 4, the P1 relay has been energized to transmit the signal to the punching machine and such relay may be energized during the time that the operator has depressed the error key to clear out storage columns representing the amount of the check. In such case the P1-2 contacts are open and although the ER3 relay contacts transfer, it will be seen that the opening of the P1-2 contacts prevents the energization of the DO1 relay. This provides for the release of the storage columns representing the digits of the amount of the check without releasing the storage columns representing the ABA number when release of the latter is unnecessary or undesirable.

Whenever the ER relay is energized it opens the ER1 contacts (Fig. 1j) to release the hold circuit of the TR relay. This conditions the alternating circuits for the C1 and C2 relays so that the next key operation will result in the energization of the C1 relay, thus, providing for the setting up of the storage columns in the proper sequence when rekeying has been effected after an error has been located.

Visible signal setup in the event operator makes one or more additional key strokes after setting up the last storage column for punching Chicago card form

5 In the event that the operator fails to depress the manual bar after making the tenth key stroke for setting up storage column 10 for the Chicago card form but makes an additional key stroke which is in error, a signal light is illuminated to call this to the operator's attention.

When storage column 10 is set up the J column relay (Fig. 1c) is energized and retained energized to maintain the J3 contacts (Fig. 1j) closed. If after setting up storage column 10 the operator makes another key stroke which would be an odd number key stroke, the C1-11 contacts (Fig. 1j) will close the C1-11 contacts (Fig. 1j). Upon the closure of both of such contacts a circuit will be closed from the line 105 through COM3 contacts now transferred (Fig. 1a), R1-2 contacts, thence by a wire 137 to the ZE3 contacts now closed (Fig. 1j), through the PE2 contacts which are now closed. The reason for the closure of contacts PE2 is that when the fifth key stroke is made the PE relay (Fig. 1a) in shunt with the P1 relay by wire 133 is energized by the circuit previously described for energizing the P1 relay. Relay PE is also held energized by a stick circuit through PE4 contacts (Fig. 1a), R4-2 contacts, back to line 105. Hence, at this time contacts PE2 (Fig. 1j) are closed. The circuit then passes from PE2 contacts, through NY5 contacts now in the position shown, thence through the C1-11 contacts now closed, J3 contacts now closed, to the grounded pickup coil of the F2 relay. The F2 relay closes the h contacts and the grounded hold coil of the F2 relay is retained energized through the h contacts, the ER4 contacts and wire 107 back to line 105. In the above circumstances the F2 relay is energized and held energized. Referring to Fig. 1k, it will be seen that energization of the F2 relay closes the F2-4 contacts, closing a circuit from the line 105, through the F2-4 contacts to the grounded "Stop" signal lamp L3. The illumination of the lamp L3 (see also Fig. 12) will give the desired indication of error to the operator.

At this time the next procedure of the operator is to depress the error key to energize the ER relay and open the ER4 contacts (Fig. 1j) to deenergize the F2 relay and extinguish the lamp L3. This act of the operator will also cause the clearing out of the storage columns pertaining to the amount of the check and rekeying of the operator then ensues to again set up the data in the storage columns.

If the operator fails to recognize the error that has been made and attempts thereafter to depress the manual bar to initiate punching operations under control of the storage columns for the amount field, it will be observed that with the prior energization of the F2 relay the F2-5 contacts are open (Fig. 1j) and since these contacts are in the impulsing circuit for the P2 relay the latter cannot be energized by the depression of the manual bar.

Error indication to operator when operator fails to make an entry in column 10 before depression of the manual bar

This error indication is to inform the operator that an insufficient number of key strokes have been made which means that all the storage columns pertaining to the setup of the check amount have not been set before the manual bar

is operated. Until storage column 10 has been set up the J4 contacts will remain in the normal position shown and the act of the operator to depress the manual bar before ten key strokes have been made will cause a circuit to be closed from the line 105, wire 107, through contacts 130 (Fig. 1a) closed by the manual bar, wire 134 (Fig. 1j), through the NY4 contacts now in the position shown, thence through the J4 contacts in the position shown, ZE1 contacts now closed, to the F2 relay, causing lamp L3 to light giving an indication of error and the necessity of a depression of the error key by the operator.

Audible signal given when too many key strokes are effected

Aside of the indication of error of the operator by lighting the lamp L3, an audible signal is provided to signal the operator when the latter continues with key operations beyond the number required to set up the ten storage columns. In other words, if the operator continues to make 11, 12 and further key depressions, a buzzer will be sounded by the following described circuit: Upon each key stroke a circuit will be closed from the line 105, through bail contacts 123 (Fig. 1a), through COM2 contacts, through CB1 contacts (Fig. 1b), wire 138 through the F2-1 contacts now closed, to the grounded buzzer B. Hence, each additional key stroke will be accompanied by an audible signal to the operator that such erroneous key strokes should not be continued.

Means is further provided to prevent erroneous setup of the K relays by such erroneous key depressions and when relay F2 is energized it will open the contacts F2-2 and F2-3 (Fig. 1a), preventing impulses from being directed to the K relays upon closure of the key operated contacts. Also the opening of such relay contacts prevents the erroneous energization of the alternating relays C1 and C2.

Error indication when storage columns 1-4 have not been cleared out and operator attempts to set up digits therein

Another type of error may be made by the operator when the latter fails to recognize that the illumination of the lamp L1 indicates that storage columns 1-4 have not been cleared out and an attempt is made by the operator to enter digits in such storage columns. It will be recognized that after the operation of the punching machine under control of the storage columns the clearing out of the latter is performed to enable a digit setup of storage columns 1-4 for the next ABA check number. However, the punching machine may yet be in operation and the condition which enables the operator to proceed with the next digit setup in such circumstances is the case where the operator proceeds more rapidly than the punching machine, or by the failure of the punching machine for any of a number of reasons.

It will also be recalled that when the operator makes the fifth key stroke, or the first key stroke for the amount field, the P1 relay is energized and is held energized until the DO1-1 contacts open to clear storage columns 1-4. Until such relay is deenergized the P1-1 contacts (Fig. 1b) are now in transferred position. Upon the attempt of the operator to enter a digit in storage column 1 which is yet uncleared, a circuit will be closed from line 105, to bail contacts 123 (Fig. 1a), COM2 contacts, wire 110 (Figs. 1a

and 1b), CB1 contacts (Fig. 1b), C1-1 contacts now closed, PE1 contacts now in the position shown, R3-3 contacts, P1-1 contacts now transferred, and a wire 139 (Figs. 1b and 1a, and 5. Fig. 1j, in the order named) to the grounded pickup winding of the F1 relay. The pickup winding closes the h contacts and a stick circuit for the F1 relay is provided from the ground, through the hold winding of the F1 relay, the h or stick contacts, through the ER4 contacts now closed and wire 107 (Fig. 1a) back to the line 105. The F1 relay when energized closes its F1-4 contacts to close, by an obvious circuit, the "Not clear" lamp L4. The lighting of this lamp will be a visible indication to the operator of the error made and operation of the error key 117E is then made to deenergize the F1 relay and extinguish the L4 lamp.

Repeated attempts of the operator to make such digit setup in the uncleared storage column 1 will also be audibly indicated because, by the circuit previously traced, the energization of the F1 relay will close the F1-1 contacts (Fig. 1j). Thereafter for each key stroke the previously described circuit to the buzzer B will be closed through F1-1 contacts, audibly indicating the error made by the operator.

Of course, the opening of the F1-2 and the F1-3 contacts (Fig. 1a) prevents the erroneous energization of the K relays as well as the C relays for each of the key strokes which are made in error.

Special interlock circuits

35 A special interlock circuit is provided to prevent an erroneous digit entry in storage column 1 when the group of storage columns 1-4 have already controlled the punching machine and have been cleared out, but the operator is still occupied 40 in effecting the entry of digits in columns 5-10 by successive key operations.

When P1 relay energizes the pickup winding of PE relay by wire 133 (Fig. 1a) is concurrently energized. PE relay closes its h contacts and through such contacts the hold winding of PE relay is retained energized by a stick circuit passing through h stick contacts, relay contacts R4-2 to line 105. Hence, the hold winding of the PE relay is held energized by an independent 50 stick circuit.

When storage columns 1-4 are cleared out after they have controlled the punching machine, the DO1-1 contacts open to deenergize the P1 relay and the P1 relay enables the P1-1 contacts (Fig. 55 1b) to come to normal. However, since the hold winding of the PE relay is still energized because R4-2 contacts are still closed, the PE1 contacts shifted by the hold winding are transferred, thus preventing erroneous entries in storage column 1 under the above circumstances. When the 60 manual bar is operated, R4 relay energizes by a circuit to be subsequently explained to open the R4-2 contacts to deenergize the hold winding of the PE relay and restore the PE1 contacts to normal.

The PE relay closes the PE4 contacts (Fig. 1a) having the following function. It will be recalled that the KB relay is utilized for storing up X designations in storage columns 5-10 for the Chicago card form and upon an error key correction in these columns the KB relay should be retained energized because its stick circuit passes through the DO2-2 contacts (Fig. 1a) which are opened upon an error key operation. The supplemental hold circuit for the KB relay (Fig. 1a)

is from its h contacts, through the PE4 contacts, through PD2 contacts now closed, COM3 contacts now in the position shown, back to line 105. The PE relay closes its PE3 contacts to close a circuit from line 105, through COM3 contacts now in the position shown, PE3 contacts, to energize the pickup winding of the PD relay. The latter closes its h contacts and a stick circuit for the PD relay extends through such h contacts and R4-5 contacts back to line 105.

Manual bar

Reference has been made to the manual bar which is depressed after setting up the storage columns for representing the amount of the check and aside from causing the energization of the P2 relay, other relays are energized as a result of the operation of the manual bar and the circuits involved will now be described.

From the previously described impulse circuit to energize P2, it will be noted that a wire connection 141 (Fig. 1j) is joined to one side of the P2 relay and the impulse is directed by this wire through R4—1 contacts now closed (Fig. 1k), to both the MBR and R1 relays, concurrently energizing both. R1 relay closes its hold contacts R1—1 and the MBR relay closes its hold contacts MBR3 and the stick circuit is extended back to the line 105 through these contacts and R4—1 contacts. Closure of such hold contacts and the closure of the MBR1 contacts closes a circuit from the line 105, MBR1 contacts to the R2 relay. The latter in turn closes its contacts R2—1 to energize the R3 relay and this in turn closes its R3—2 contacts to energize the R4 relay. The latter closes its *h* or stick contacts and a stick circuit is extended back to line 105 through MBR3 and R1—1 contacts. Hence, regardless of how momentary the operation of the motor bar, relays R1 and MBR are held energized through MBR3 and R1—1 contacts until completion of the chain of events terminating in the energization of the R4 relay. When R4 relay finally energizes, its R4—1 contacts open and de-energize the R1 and MBR relays with consequent deenergization of relays R2 and R3. If the pressure on the manual bar has been released in the interim, R4 relay will likewise deenergize. If the manual bar is held down by the hand of the operator for an extended period, R4 relay remains energized through its *h* stick contacts until release of the manual bar is effected and such circuit is provided to prevent repeated energization of R1 and MBR relays.

The function of the R3 and R4 relays involving the previously described circuits consists in the opening of the R3-1 contacts (Fig. 1*j*) which causes the deenergization of the TR relay to insure correct restarting of the alternating sequence of C1 and C2 relays. The R4 relay opens its contacts R4-2 (Fig. 1*a*) to break the stick circuit of the PE relay, and R4-5 to break the stick circuit of the PA relay.

Card punching machine

The card punching machine P (Fig. 12) used in connection with the present invention is of the type shown in the patent to Fred Lee and George Daly, No. 1,976,618, dated October 9, 1934, modified for the purposes of the present invention according to the patent to O. B. Shafer, No. 2,315,-741, dated April 6, 1943, and only so much of the operation thereof will be explained as is necessary for an understanding of its operation in connection with the present invention.

In general, the punching machine includes a feed magazine 53 (Fig. 7) from which, as is well known, the cards are fed singly from the bottom of the magazine by a picker. In the present machine the card carriage moves in the usual manner to present the first card column of both the New York form of card and the Chicago form of card to the punches 55 preparatory to receiving the perforations effected by the first punching operation. From this position, the card is engaged at its rear edge by a pusher 54 mounted upon an escapement rack 56 which, for successive operation of the punches, permits the advance of the card step by step. The series of magnets 182 is adapted to select the punches 55 for actuation in the following manner: Associated with each magnet 55 is a pivoted armature 51 whose free end is connected to a rod 58 which, through a bell crank 59, moves an interposer bar 60 to the left in Fig. 7 where it cooperates with a punch bar or plate 61. The forward movement of the interposer bar 60 is adapted to rock a bail 62 pivoted on a rod 63 which bail is connected to a spring pressed depending link 64 whose lower free end is adapted to engage and close contacts 65. This, as shown in Fig. 11 closes a circuit from the line 105, through contacts 65, through the magnet 66 to ground. Energization of the magnet 66 will then attract its armature 67 (Fig. 7) and through a link and bell crank connection 52 (shown completely in the aforementioned patent to Lee et al.) will draw downwardly on the pivoted punch bar or plate 61 to force the selected interposer against the associated punch, thus perforating the card.

The selection of the magnets 182, which are punch selectors for effecting the punching operation, is under control of the translators pertaining to the related storage columns and such translators are read out column by column to effect successive card punching operations. In accordance with the selective plug connections to be later described, a control from the multiple keyboard is rendered effective to select the punches for operation to punch certain columns of the card in the same step-by-step manner.

As is fully shown in the patent to Lee et al., No. 1,976,618, when the armature 67 (Fig. 7) reaches the limit of its movement to the right the link 64 will be moved by projection 52a to become disengaged from one of the spring blades of contacts 65 to permit such contacts to open, thereby deenergizing the magnet 66 which will then release its armature, allowing the spring 68 to rock the plate 61 upwardly and permit the operating end of the selected interposer 60 to rise and thereafter be restored to normal position by a spring 69.

Escapement mechanism.

The escapement mechanism is not shown herein since it is well known and fully shown and described in the Patents Nos. 1,976,618 and 2,315,741 herein mentioned and Patent No. 1,426,223. It will suffice to say that when an interposer 60 is depressed it will rock a ball 70 attached to shaft 71 and the rocking of this shaft will actuate the escapement mechanism to space 70 the card carriage and card carried thereby a single column.

Column selector

The column selector for the punching machine illustrated herein is also well known and is shown

in the patent to G. F. Daly, No. 2,016,706, dated October 8, 1935. As is shown in Fig. 7 as well as in Fig. 1*h*, it consists of a movable contact brush 188 carried by the punch carriage engageable with contact points 189, all of which are connected to plug sockets 191 and certain of which plug sockets have plug connections made thereto so as to cause punching operations to be effected for such card columns.

Incidental operations in punching machine

These operations consist of the closing of contacts 76 (Fig. 1*i*) which are closed in the last column position of the card carriage and which contacts are the same as contacts 191 of the Patent No. 1,976,618 and closed in the manner described in this patent. The closure of contacts 76 energizes the card eject control trip magnet 77 which corresponds to magnet 199 of the aforementioned patent.

As the card is ejected, contacts 78 herein corresponding to contacts 201 of the aforementioned patent will complete a circuit to magnet 79 which corresponds to magnet 175 of the Lee et al. Patent No. 1,976,618.

Magnet 79 (Fig. 7) will attract its armature 80 and the arm thereof will bear upon an insulating block to open contacts 184 and close contacts 190 precisely as in the last mentioned patent. Contacts 190 now being closed close a circuit to the motor 157 (Figs 1*i* and 7) which is the same motor in the Patent No. 1,976,618 and similarly designated. At the same time as is well known and explained in patent No. 1,976,618, arm 81 effects the engagement of the clutch between this motor and the moving mechanism for the card carriage which automatically feeds a blank thereon for the next card punching operations, and returns the carriage to an initial starting position.

These incidental operations are explained herein partly by reference to Fig. 1*i* for the wiring connections of the elements involved to effect these incidental operations and reference to Fig. 7 for the more important elements of the punching machine which are recognized as performing the fundamental operations of the machine. These operations in the form of punching machine selected as an embodiment are very well known and recourse to the patents referred to give further details of the construction and operation.

Card punching machine (continued)

For punching the card according to the Chicago form, column 1 is immediately under control of the multiple keyboard so that punching of the digit setup of the storage columns 1-4 commence from card column 2 and continues successively through column 5 of this card. It will be noted, therefore, that storage columns 4, 3, 2 and 1 control punching of card columns 2, 3, 4 and 5, respectively, because punching is effected reversely with regard to the denominational setup. Punching operations from storage columns 1 to 4 are initiated immediately upon completion of the 5-key stroke. Punching of card columns 8 to 13 under control of storage columns 5 to 10 is effected immediately upon completion of setting up these storage columns and after the manual bar is depressed. However, before card columns 8 to 13 are punched, columns 5 to 7 of the card are punched under control of the multiple keyboard and follow automatically after punching column 4. When card

column 7 of the Chicago card form has been punched the carriage will space to card column 8 and automatic punching operations for columns 8-13 will be effected only after the manual bar is depressed and P2 relay is energized. Tabulated, the punching operations are effected as follows:

Upon completion of setting up of column	Relay coil energized	Storage columns read out	Card columns punched
5.....	P1	4, 3, 2, 1	2, 3, 4, 5
10 and manual bar depressed.....	P2	10, 9, 8, 7, 6, 5	8, 9, 10, 11, 12, 13

In the present machine all of the cards punched according to the Chicago card form are punched in the first card column with data which is common to a series of cards and by means of the well known carriage return mechanism the carriage, when it is returned to the initial position, enables punching operations to be effected under control of the multiple keyboard to punch card column 1 and thereafter the card carriage automatically spaces to card column 2.

Multiple keyboard

The multiple keyboard MK (Fig. 12) is provided to enable punching of certain card columns with the same data and such form of keyboard is well known in its construction and operation and consists in the present machine of seven banks of keys 200, each denominational bank of keys representing the digits 0-9. Each key when depressed is held latched by a well known construction so as to retain related contacts 201 (Fig. 1*e*) closed. One side of each of the contacts for each denominational bank of keys is connected to a wire 202 whereas the other sides of the contacts of all banks of keys having the same digit value are interconnected by wires 203 and such wires representing the digits 9-0 inclusive are in a cable 204 and these wires are connected to the related digit punching magnets 182 (see Fig. 1*e*). Obviously, the depression of a digit key in a particular denominational order will close its contacts 201 so that, through the related digit line 203, the related punch magnet 182 will be selected for operation. A readout for the keyboard operated contacts is effected in succession column by column and under control of the punch carriage to punch selected columns of the card.

Card punching operation—Chicago card form

Successive punching operations of the punching machine are effected under control by a device known as "a column readout device" which is well known in the form of punching machine described and is fully shown in Fig. 3 of the patent to G. F. Daly et al., No. 2,016,706 and reference may be had thereto for further details.

Referring to Fig. 1*i* it will be noted that from the line 105 a circuit extends to contacts 184, wire 142, to card lever relay control contacts CL1, now closed, to contacts 185, thence to a wire 187. Contacts 184 correspond to the contacts designated 136 in Patent No. 1,976,618 and are operated similarly and have corresponding functions herein. Contacts 185 are similar in operation and function to contacts designated 128 in Patent No. 1,976,618. Both contacts 184 and 185 are normally closed. The wire connection 187 extends to the movable brush 188 (Fig. 1*h*) of the column readout device and the brush consists of a set of four brush strands which successively make contact with the contact points 189 which are fixed. As

the card carriage steps column by column the brush strands will make successive contact with the contact points 189. All of the contact points 189 have wire connections to plug sockets 191 and for column 1 it will be noted from Fig. 8 that there is a plug connection 204 from the column 1 socket 191 of the readout to the plug socket 206 associated with the 1 bank of keys. The previous return of the card carriage to column 1 now provides a circuit from line 105, through contacts 184 now closed, wire 142, thence through relay contacts CL1 closed in a manner to be subsequently explained, thence through contacts 185, wire 187 to the brush 188 (Fig. 1*b*) contacting the contact point 189 at column 1 position, to the plug socket 191 for column 1, thence through the plug connection 204 (Fig. 8) to the socket 206 for the 1 denominational bank of keys, the wire 202 (Fig. 1*e*) for this bank of keys, thence through the contacts 201 closed by the particular key in the bank which has been depressed, through the related digit line 203, to the related punch selecting magnet 182 to ground. The punch now perforates column 1 according to the key depressed and the card column escapes in the usual manner to column 2. At column 2 a circuit is completed to punch, under control of the translator associated with storage column 4 provided that storage columns 1, 2, 3 and 4 have been completely set up.

Translators

It should be understood that the punching machine in this patent punches cards according to the Hollerith system, that is, a perforation is placed at a differential location to represent the digits set up in the storage columns. For this reason, a combinational setting of the relays 1-4 in each storage column must be translated to a single digit representation. Such forms of translators are well known and briefly for storage column 1 the energized relays 11, 12, 13, and 14 (Fig. 1*f*) transfer their respective 1, 2, and 3 translator contacts and such contacts are closed in combination in accordance with the code of relays K1-K4 energized and being interconnected in combination select one of a series of digit lines 180 which are marked 0-9 inclusive. The digit lines 180 are connected to the punch magnets 182 (see Fig. 1*f*). Therefore, according to the particular contacts of the translator which are opened and closed, one of the digit lines 180 will be selected to cause the energization of the desired one of the punch selecting magnets 182. It should be noted that in the event that digits 1-9 are not stored in a particular storage column, all the relay contacts of the translator relating to that storage column will be at normal position so that normally the 0 punch selecting magnet 182 will be selected for operation. Taking, for example, storage column 1, it will be noted that due to the normal closure of contacts 11-1, 12-1, 13-1 and 14-1 (Fig. 1*f*) there will be a normal connection through such contacts to the "0" digit line 180, thereby selecting the 0 punch selecting magnet 182 for energization. If other relay contacts in this translator are closed, another circuit will be closed through such contacts to select the appropriate digit line 180.

Each of the translators for storage columns 4-15 has extra contacts 41-4 which when transferred close a circuit to line 243, for a purpose to be made clearer later on.

Reference has been made to the fact that

punching of the card columns is effected reversely and such operation is performed by reason of the particular plug connections made between the plug sockets 191 of the card columns to be punched and the plug sockets 207 of the translators. All the plug connections for the Chicago card form are shown in Fig. 8 which should be followed in the subsequent description. From column 2 plug socket 191 of the punch readout (see Fig. 8), there is a plug connection 208 to a plug socket 209, and from a plug socket 210 there is a plug connection 211 to the plug socket 207 of the translator of storage column 4. It will be noted from Fig. 1*a* that contacts P1-3 are shunted across the plug sockets 209-210 and upon the closure of such contacts it will be seen that a circuit will be closed to cause punching operations to be effected under control of the translator for storage column 4 to punch card column 2. This particular form of plug connection is made for initiating punching of both the ABA number field (and as will be later described the amount field) so that punching the related card columns cannot be initiated until 25 relays P1 and P2 are energized. It is evident that the plug connections made to plug sockets 209-210 make it impossible to initiate punching of the ABA number field in columns 2, 3, 4 and 5 until the contacts P1-3 have closed.

When card column 2 has been punched the carriage spaces to card column 3 and by reason of the plug connection 212 (Fig. 8) made between plug socket 191 for column 3 of the punch readout and the plug socket 207 for the translator of storage column 3, punching of card column 3 will be effected and the carriage spaces to card column 4 and by the plug connection 213 the translator related to storage column 2 will control the punching of card column 4. The card carriage now spaces to column 5 at which point a special plugging is made from the plug socket 191 of column 5 of the readout to enable punching to be effected both under control of storage column No. 1 and the second denominational 45 bank of keys of the multiple keyboard and in the present machine this can be effected without misoperations taking place, due to the inherent back circuits.

When the brush 188 of the readout reaches column 5, the circuit is extended from the readout by a plug connection 215 to a plug socket 216 which completes a circuit to the grounded DP relay shown in Fig. 1*a*. This relay energizing at this column position of the readout closes its 55 DP1 and DP2 contacts and each of said contacts has circuit connections to plug sockets 217 and 218. From the plug socket 217 to the plug socket 207 for the translator of column 1 there is a plug connection 219 and from the plug socket 218 to the plug socket 206 for the second denominational bank of keys of the multiple keyboard there is a plug connection 220.

It will be seen then that for the DP1 contacts now closed a circuit will be closed from the line 60 105 (Fig. 1*a*) through the DP1 contacts, to the plug socket 217, thence through the plug connection 219 to the plug socket 207 for the translator of column No. 1, thence under control of this translator a punch selecting magnet 182 will be 65 energized. Also, a circuit is closed from the line 105 through DP2 contacts to plug socket 218, plug connection 220 and thence through the closed contacts of the second denominational bank of keys, a related punch selecting magnet 70 182 will be selected for operation. Hence, double

punching of card column 5 will be effected in this manner without the possibility of misoperations.

After card column 5 has been punched the carriage spaces to column 6 and by means of the plug connection 222 the closed contacts of the third denominational bank of keys of the multiple keyboard will control punching in card column 6. The card carriage then spaces to column 7 and by means of the plug connection 223 card column 7 will be punched under control of the closed contacts of the fourth bank of keys. The card carriage now arrives at card column position 8 and if the manual bar has been operated, contacts P2-2 (Fig. 1a) will be closed and by reason of similar plug wire connections 224-225 made to plug sockets 226 shunted across such contacts (see also Fig. 1a), initiation of punching of card column 8 will be effected under control of storage column 10. Punching in reverse denominational order then ensues under control of the translators for storage columns 5-9 by reason of the reverse plug connections made between plug sockets 191 for card columns 9, 10, 11, 12 and 13 and the respective translators for storage columns 9, 8, 7, 6 and 5. Assuming that all of the storage columns 5-10 have been set up to represent digits of the amount, successive punching will ensue until the carriage spaces to column 14. At this column position the usual carriage skipping mechanism for the form of machine shown will then be operative and the card carriage will skip to the last column position.

Release of storage columns 1-4 upon completion of punching card columns 2-5 for Chicago card form

The energized storage relays and column relays which are used for punching the ABA number are deenergized to permit further digit set-up of such storage columns when the carriage escapes to card column 9. This is effected by the energization of the dropout relay DO1 in Fig. 1i. In the present circuit arrangement this relay is energized when the card carriage escapes to card column 9, although other card column positions may be used, and the energization of the DO1 relay is the instrumentality for then causing the punching of card column 9 under control of the translator of storage column 9, as will now be described.

To this end there is a plug connection 227 from the plug socket 191 of column 9 of the readout to a plug socket 228. From the plug socket 228 (Fig. 1j) there is a wire connection 231 to the grounded DO1 relay. Hence, upon the carriage arriving at the card column 9 position, an impulse will be directed through the column readout, through plug connection 227, plug socket 228, wire 231 to energize the DO1 relay. Energization of the DO1 relay opens its DO1-1 contacts (Fig. 1k) which deenergizes all of the storage relays for storage columns 1-4 as well as the column relays A, B, C and D pertaining thereto, and the P1 relay. The opening of the DO1-3 contacts (Fig. 1k) and D5 contacts opens the energizing circuit for the L1 lamp, causing such signal light to be extinguished, thus indicating to the operator that storage columns 1-4 are now cleared, and enables a subsequent ABA number digit setup for the next check provided, as has been described heretofore, that the operator is not still occupied in setting up storage columns 5-10.

Closure of the DO1-2 contacts (Fig. 1j) also

enables the energizing impulse transmitted to DO1 to be transmitted through the ER3 contacts now in the position shown, thence through the DO1-2 contacts so that when the latter contacts close the circuit is closed to a plug socket 232. From this plug socket there is a plug connection 233 (Fig. 8) to the plug socket 207 of storage column 9. The translator associated with this storage column will enable card column 9 to be then punched.

Release of storage columns 5-10 upon completion of punching card columns 8-13 for Chicago card form

Upon punching card column 13 the card carriage spaces in the regular manner to column 14, provided that preceding storage columns have not been set up to represent X. In the omission of X setup, a circuit is closed upon the carriage spacing to column 14, described as follows: From the plug socket 191 of the readout for column 14 there is a plug connection 235 which terminates at plug socket 236 and which latter (Fig. 1k) has a wire connection 237 to grounded relay R6. Hence, at the column 14 position of the card carriage the R6 relay will be energized to close R6-3 contacts (Fig. 1i), and thus a circuit will be closed from the line 105 through contacts 184, wire 142, through contacts R6-3, to the grounded skip magnet 238 energizing the latter to initiate a skipping operation of the card carriage to the last column position of the carriage. Skip magnet 238 is similar in function to the skip magnet designated 56 in Fig. 7 of the patent to O. B. Shafer, No. 2,315,741, dated April 6, 1943. The action of this skip magnet is to shift the usual skip lifter and the card carriage will then be released under control of a "high bar" for uninterrupted movement to the last card column position because the skip bar is provided with a high portion for such skipped over columns.

It is desirable that during this skipping operation the circuit connection to the column readout be opened and this is provided for by the R6-4 contacts (Fig. 1i). This will close a circuit from the line 105, through contacts 184 (Fig. 1i), wire 142, through CL1 contacts now closed, contacts 185, thence through the R6-4 contacts to the punch magnet 66. The energization of the punch magnet will cause, through the escapement mechanism operated thereby, the positioning of the so-called floating cam designated by reference numeral 119 in Fig. 4 of the patent to F. Lee, et al., No. 1,976,618 and such positioning of the cam will cause contacts 128 therein to open, or the opening of contacts 185 herein. The opening of contacts 185 in the present circuit will open the wire circuit 187 to the column readout brush 188 so that false circuits cannot be closed during the skipping of the card carriage to the last column position, or in the positioning to the first card column. When the first card column position has been obtained the escapement mechanism will be normalized and contacts 185 are closed to immediately punch card column 1 of the next card.

Reverting now to the release of the storage columns 5-10 for punching the amount of the check, energization of the R6 relay (Fig. 1k) transfers the R6-2 contacts and this will close a circuit from the line 105, wire 239, through contacts R6-2 to relay R7. Relay R7 holds through the hold contacts R7-2, R8-1 contacts now closed, and wire 239 back to line 105. Relay R7, now being energized, closes its con-

tacts R7-1 (Fig. 1g). It is evident that as the card carriage skips, the energizing circuit for the R6 relay will be opened and R6-2 contacts come to normal position and a circuit will be closed from line 105, wire 239, through R6-2 contacts now at normal, R5-2 contacts now at normal, wire 240 (Figs. 1g and 1k), through R7-1 contacts, to the DO2 relay. DO2 relay will transfer its contacts DO2-1 (Fig. 1c) and a circuit will be closed from line 105, DO2-1 contacts, wire 242 (Figs. 1c, 1b, 1k in order named), to the R8 relay. R8 relay will then open R8-1 contacts, breaking the hold circuit for the R7 relay which, upon its deenergization, opens its contacts R7-1 to deenergize DO1 relay. In this manner, a complete energization of relay DO2 is assured to secure the desired functions which will now be described.

The transfer of DO2-1 contacts (Fig. 1c) breaks the holding circuit wire 104 for storage columns 5, 6 and the holding circuit wire 264 for storage columns 7, 8, 9 and 10 and thus deenergizes the storage relays for storage columns 5-10 as well as the related column relays E, F, G, H and I and the KE relay. Opening of the DO2-2 (Fig. 1a) contacts also breaks the holding circuit for the P2 relay and the KB relay in the event that the latter was used for X representation in certain storage columns.

In respect to the skipping of the card carriage and the energization of the DO2 relay to release the associated storage columns, the machine operates differently when certain columns are set up to represent X to save time in punching machine operations and the manner in which the machine operates under such circumstances will now be described in detail.

Skipping of card carriage and release of storage columns 5-10 when selected card column of Chicago card form is to be X-punched

The operation of the punching machine when all amount card columns 8-13 of the Chicago card form are punched has just been described but an alternative method of punching the amount field has been referred to. The same plugging connections are made as shown in Fig. 8, but the operator merely alters key depressions for checks having small size amounts. This procedure, it will be recalled, consists in depressing the zero key 111 one or more times for setting up one or more of the initial storage columns 5, 6, 7, etc. to store up in each an X representation followed by digit setup in the remaining storage columns of the amount of the check. For example, digit setting of the amount \$5.00 is represented in storage columns 5, 6, 7, 8, 9 and 10 for digit and character settings as follows: XXX500, respectively. In reading out the translators of the respective storage columns, the storage columns are read out in reverse denominational order and columns 8, 9 and 10 are punched to represent 005. Following punching in card column 10 the translator for storage column 1 having the first X representation is read out and is effective to cause the operation of the X key in the punching machine which initiates in a well known manner card carriage skipping operations. While storage column 1 has been referred to in this example for receiving X representation, of course this storage column may vary according to the size of the amount of the check but the first storage column read out which has an X setup is the initiating instrumentality for carriage skipping and while the remaining storage

columns also have the same character set up they are ineffective.

It will also be recalled that the depression of the 0 key 111 of the ten key keyboard causes the energization of the K1-K4 relays by the circuits previously described, resulting, in the assumed example, of the energization of relays 81 and 84 of storage column 7. When the card carriage is spaced to column position 11 the column readout device is then effective to transmit an impulse to the plug socket 207 for the translator of column 7 and with contacts 74-1 and 71-1, 2, 3 and 4 transferred (Fig. 1g), the circuit will be closed from such plug socket 207 through contacts 74-1 now transferred, contacts 73-2 now at normal, 72-3 now at normal, thence through 71-4 contacts now transferred, to wire 243 (Figs. 1g, 1f, 1b, 1k in order named) to the R5 relay. R5 relay closes R5-1 contacts and the same impulse is directed through the R5-1 contacts, to wire 244 (Figs. 1k, 1b, 1g, 1h, 1i, in order named), which leads to the X punch magnet 182 energizing the latter. It is well known that the energization of this magnet will incidentally herein perforate the card at the X index point position or column 11 herein. The principal reason herein is to effect the energization magnet 182X to operate the X key of the punching machine. It is well known from Patents No. 1,962,750 and No. 1,772,186 that the energization of magnet 182X effects the depression of the X key which renders the usual escapement mechanism operative and enables the card carriage to be skipped under control of a high portion of the skip bar from such column position to the last card column position. Hence, skipping over one or more card columns saves time in the operation of the punching machine.

Card lever contacts and magazine contacts in punching machine

It is common to provide a card lever which is mounted on the punch bed of the punching machine and when the card has been fed from the magazine 53 to such position this card lever 163 (Fig. 1i) will be operated to close contacts 164, thereby closing a circuit from the line 105 through contacts 164 to grounded CL relay coil. A stick circuit is provided for the latter through CL2 contacts, wire 142, contacts 184, back to line 105. The energization of the CL1 relay closes the CL1 contacts involved in the circuits previously described.

It is preferable to provide in the punching machine contacts such as contacts 175 which are open whenever there is a card in the magazine 53. When the last card has been fed, pressure on the lower blade of the contacts 175 is relieved, thereby enabling contacts 175 to close, completing a circuit from line 105, through contacts 175, thence by wire 176 (Figs. 1i, 1e, 1d, 1c, 1b, 1a in order named), wire 139 (Figs. 1a, 1j) to the F1 relay. It will be recalled that when this relay is energized it will close its F1-4 contacts, (Fig. 1k) illuminating the not clear signal light 14 giving a visible indication to the operator of the condition of the card magazine. Other circuits are controlled by the F1 relay previously described which give an audible signal when key strokes are effected by the operator and also to prevent such false key operations from setting up the storage relays. Thus, proper signals are given to the operator when cards in the magazine are exhausted, necessitating the operator to take the proper corrective measures.

Punching card according to the New York form

The New York form of card is represented in Fig. 5 in which it will be seen that the fields vary from the Chicago card form in number of columns. By making the plug connections shown in Fig. 9, the punching pattern may be changed by reason of different energizing circuits for the instrumentalities in the punching machine. It will be observed from a comparison of Figs. 8 and 9 that the association between the column readout of the punching machine and the plug sockets of the storage columns, keyboard and other controlling plug sockets is quite different and the inherent flexibility of such plug connections enables the punching machine to punch different forms of cards, represented by two examples in Figs. 5 and 6.

An examination of Fig. 5 will show that the New York card form consists of twenty card columns of which six columns are punched under control of the keyboard, whereas a maximum of fifteen columns may be punched under control of the storage relays. Like the provision for the Chicago card form, double punching is effected but in column 6 one punching controlled by the keyboard and the other punching from the plugged up storage column. The first two card columns of the New York card form consist of a state number punched under control of storage columns 1 and 2. Card columns 3, 4, 5 and 6 are punched under control of respective storage columns 6, 5, 4 and 3 to enable reverse punching for the reasons explained for the Chicago card form. Card columns 6-11 are punched under control of the multiple keyboard to represent the ABA number and state of the sending bank. The amount field consists of nine columns 12-20 and the manner in which punching is to be effected in such card columns under control of the storage columns depends upon the amount or value of the check and the inspection of amount on the check guides the operator in making selective controls for punching the amount field so that time will not only be saved in setting up the digits of the amount in the storage columns but there will be a saving in time in the operation of the punching machine when the card columns of the amount field are punched. Thus, various forms of punching may be effected, all with the viewpoint of saving time.

Punching of data in card columns 1-6—New York card form

There was previously described the impulsive circuit provided for the storage columns 1-6 and such storage columns are successively set up as the key depressions are made for punching the New York card form and in view of the previous circuit descriptions for setting up storage columns 1-6 for the Chicago card form, repetition of such description is unnecessary.

The plugging arrangement for the New York card form is shown in Fig. 9 and referring to Fig. 9 it will be observed that the plug connections 245, 246 are made from plug sockets 1 of the punch readout sockets 191 and translator sockets 207 to the respective plug sockets 209, 210. Such plug connections enable the initiation of punching of card column 1 and subsequent card columns up to and including card column 11 under control of storage columns 1-6 and the multiple keyboard columns 1-6 when a certain storage column has been set up, to be later

described. By means of the plug connection 247, card column 2 is punched under control of storage column 2. By plug connections 248, 249, 250, 251 card columns 3, 4, 5 and 6 are punched under control of the storage columns 6, 5, 4 and 3 respectively and punching from storage columns 3-6 is effected in reverse denominational order. It should be noted that column 6 of the New York card form is double punched and therefore the plug connection 251 is made between plug socket 6 of the punch readout and the plug socket 216. The plug connection 252 between plug socket 217 and the plug socket 207 of storage column 3 enables punching of card column 6 under control of the translator of storage column 3, whereas the plug connection 253 enables the same card column 6 to be punched under control of the 1 denominational bank of keys.

As will be subsequently explained, when the card carriage is positioned to card column 1, no punching operations are effected until the punch start relay P1 is energized by a circuit to be subsequently described. However, upon initiation of punching operations card columns 1-6 are automatically punched and upon completion of punching card column 6 the card column spaces to card column 7. By the group of plug connections 254, automatic punching operations then ensue under control of the denominational bank of keys 2, 3, 4, 5, and 6 to punch card columns 7, 8, 9, 10 and 11. Thereafter, the card carriage spaces to column 12 which is the initial card column for punching the amount of the check, and punching stops until P2 relay is energized by a circuit to be described. However, digressing to the setting up of the storage columns for representing the amount of the check, in conditioning the punching machine for punching the New York form of card upon completion of setting up of storage columns 1-6, the seventh key stroke causes the impulse to be directed to storage column 11 instead of column 7, as for the Chicago card form. This skipping of storage columns 7, 8, 9 and 10 is effected by the energization of a relay designated NY in Fig. 1e. By means of a plug connection 256 (Fig. 9) the grounded NY relay (Fig. 1e) is connected to the current line 105. Distributed throughout the controlling circuits are contacts of the NY relay and the transfer of the NY contacts shown in Fig. 1c enables, by a circuit to be described in detail hereinafter, the impulse created by the seventh key stroke to be directed to storage column 11.

This results in skipping of storage columns 7, 8, 9 and 10 to proceed with setting up of digits in storage columns 11, 12, 13, 14 and 15 in this named order. This limits the punching to five card columns, 12, 13, 14, 15 and 16 of the amount field and since plug connections for the New York form are made reversely, it will be observed that punching of the first five card columns 12-16 of the amount field of the New York form of card ensues in a reverse manner. The skipping of storage columns 7-10 makes it unnecessary for the operator to depress the zero key one or more times to set up unused storage columns 7-10 and thus provides for punching of only the first five card columns 12-16 of the amount field.

Limiting the punching to five columns enables time saving in punching of the amount field because while nine card columns of the amount field are allocated at times for the amount of the check, a great majority of the checks are

relatively small in denomination. Further savings in time for punching operations ensue because when cards representing small amounts of the check are punched it is possible in a manner to be subsequently described to cause skipping of the remaining unused card columns of the amount field in the operation of the punching machine.

At this time, the impulsing circuit for setting up storage columns 11, 12, 13, 14 and 15, and omitting storage columns 7, 8, 9 and 10, will now be described. It will be recalled that for the New York form of card the NY relay is energized. Storage columns 1, 2, 3, 4, 5, and 6 are set up consecutively as previously described and upon the seventh key stroke the impulse is directed from the CB1 contacts, (Fig. 1b) wire 108, through C1-4 contacts (Fig. 1c) now closed because this is an odd key depression, F1 contacts now closed because of the setting up of a digit in storage column 6, thence through the ZE8 contacts now at normal, thence through the NY11 contacts now transferred, through the X4 contacts now at normal position, wire 257 (Fig. 1c) thence through L2 contacts now closed, to energize the 111-114 storage relays of column 11, depending upon the digit key depressed. Following the digit storage in column 11, successive storage impulses proceed by wire 108 in the normal manner for following key strokes to storage columns 12, 13, 14 and 15 in succession while no storage impulses can be directed to column 7, due to the interruption of the impulse feed circuit to column 7 by the transfer of contacts NY11. It will also be observed that the opening of the NY10 contacts (Fig. 1b) opens the feed impulse wire 109 and prevents any of such impulses from being transmitted to storage columns 8, 9 and 10. Opening of K3 contacts (Fig. 1c) by the K column relay when storage column 11 is set up prevents an improper setup in storage column 6 when setting up storage column 12 and when storage columns 7-10 are skipped.

When the machine is plugged up for punching the New York card form, a circuit is employed which is different from the one utilized to energize the P1 relay (Fig. 1a) when punching the Chicago form of card. When punching is effected according to the New York card form the NY relay is energized and the NY6 contacts (Fig. 1a) are transferred. When storage column 13 is set up, and which is accomplished upon the third last key stroke of the amount digit set up, column relay M will be energized and held energized to retain the M3 contacts (Fig. 1a) closed. When the second last key stroke of the amount digit setup is made, the C2 relay is energized because this is an even numbered key stroke and it results in the closure of the C2-12 contacts (Fig. 1a). Therefore, upon the second last key stroke of the amount digit set up, a circuit will be closed from line 105 through COM3 contacts, through NY6 contacts now transferred, and thence through the ZE4 contacts now in the position shown, through C2-12 contacts now closed, through M3 contacts now closed, thence by wire 135 to the PD1 contacts, thence by wire 133 to the pickup winding of the P1 relay. The energization of this relay closes its P1-3 contacts (Fig. 1a) to thereby initiate a punching operation for column 1 and subsequent columns which successively ensue to punch card columns 1-11, inclusive and then stop unless P2 relay is energized. Such column punching is effected both under control of the six storage columns

set up and the six denominational bank of keys of the multiple keyboard.

When storage columns 1 to 6 have been utilized for controlling punching operations, it is desirable that they be deenergized and this is accomplished when the card carriage spaces to card column position 13. A plug connection 258 (Fig. 9) is made between plug socket 13 of the punch readout and plug socket 228 (see also Fig. 1j). This, it will be recalled, transmits an impulse to the DO1 relay. By virtue of the plug connection 259 (Fig. 9) between the plug socket 232 and the 14 plug socket of the storage columns, punching of card column 13 may be effected under control of storage column 14.

It will be recalled that for the Chicago card form the holding circuits for storage columns 5 and 6 were controlled by the DO2-1 contacts (Fig. 1c). When the machine is conditioned for punching the New York card form, the NY12 contacts (Fig. 1c) transfer and therefore the holding circuit for storage columns 5 and 6 will now be directed from line 104, through the NY12 contacts now transferred, to the wire 111 (Fig. 1c) which continues a holding circuit through the DO1-1 contacts, back to line 105. Hence, with NY12 contacts transferred, the opening of the DO1-1 contacts will not only deenergize storage columns 1 to 4 but also storage columns 5 to 6, all of which storage columns, it will be noted from Fig. 5, are used to represent the digits of the state number and the ABA number of the paying bank.

In punching the New York card form, after punching card column 11, the punch carriage spaces to card column 12 but punching of this card and the succeeding card columns of the amount field does not take place until the P2 relay is energized.

Contacts P2-2 (Fig. 1a) are shunted across the plug sockets 226. Therefore, punching of card columns 12 on cannot be effected until the P2 relay is energized to close the P2-2 contacts.

From Fig. 9, it will be seen that a plug connection 260 is made between plug socket 12 of the punch readout and one of the plug sockets 226. The other plug socket 226 has a plug connection 261 to plug socket 15 of the storage columns.

The circuit to energize the P2 relay (Fig. 1j) for the New York card form is also closed when the manual bar 118 is depressed to close its contacts 130 (Fig. 1a). When storage column 15 receives a digit setup, which is performed by the key stroke effected just prior to depressing the manual bar 118, column relay 0 will be energized and retained energized so as to transfer the O4 contacts (Fig. 1j). Hence, with NY4 contacts and O4 contacts now transferred the impulse proceeds from contacts 130 (Fig. 1a), thence by a wire 134 (Fig. 1a, Fig. 1j) to the transferred NY4 contacts, through O4 contacts now transferred, through ZE2 contacts now in the position shown, thence through F2-5 contacts to the P2 relay. This relay closes its P2-2 contacts (Fig. 1a) and punching of card column 12 then ensues and also the subsequent card columns 13, 14, 15 and 16.

As shown in Fig. 9, the plug connections which include the plug connections 260, 258, and 262 are made between card columns 12-20, inclusive, and also storage columns 7-15 inclusive so that amount field punching will take place under control of the storage columns 1-15 in reverse denominational order.

When a decreased number of card columns or

12 to 16 of the amount field of the New York card form are utilized, carriage skipping operations take place from card column 16 in a manner to be subsequently described in detail. When the carriage skips past the card column 21 position, a circuit is closed from the 21 plug socket of the punch readout (Fig. 9), through a plug connection 263 which terminates at the plug socket 236, also shown in Fig. 1k. It will be recalled that this eventually results in the energization of the DO2 relay which opens its DO2-1 contacts and deenergizes the storage columns set up for the amount representing field. From Fig. 1c it will be seen that wire 264 is the holding circuit wire passing through DO2-1 contacts back to line 105 for storage columns 7-15.

X-punching in shortened amount field of New York form of card

In the preceding description an arrangement was described wherein storage columns 11-15 were allocated for receiving five digits of the amount of the New York form of card where the amount of the check does not exceed five denominational orders. Sometimes the amount of the check is even smaller, such as \$5.00 and saving in time in card punching operations is effected by setting up X representations in storage columns preceding the first significant digit by depressing the 0 key 117 one or more times. In the above example storage would be effected as XX500 and in punching the card it would be represented in columns 12-16 (Fig. 5) as 005XX. The X setup in storage column 12 would be the instrumentality for causing skipping of the card carriage in the manner previously described. In view of the fact that the circuit is somewhat different from that described for the Chicago card form it will now be described as utilized for the New York card form. Upon making the sixth key stroke, in setting up storage column 6 to represent the last digit of the ABA number relay F is energized to close the F4 contacts (Fig. 1a) and upon release of the pressure on the key used for the sixth stroke CB2 contacts will come to normal and a circuit will be closed from line 105, through DO2-2 contacts, CB2 contacts now closed, NY1 contacts now transferred, F4 contacts now closed, to the pickup coil of the KB relay. It will be recalled that the KB relay closes the KB1 contacts (Fig. 1a) and since as previously stated the KB relay is held energized during successive 0 key depressions, the KB1 contacts will be closed to cause the K10 relay to be energized. It will be recalled that this relay closes its contacts K10-1 and K10-2 (Fig. 1a) to energize the K1 and K4 relays and in the present example the relays in storage columns 11 and 12 will be energized. When punching of the New York card form is effected in the above example the X storage in storage column 12 will, as previously stated, cause punching in card column 15 at the X index point position, as well as the depression of the X key in the punching machine to skip the carriage to the last column position.

In utilizing the shortened amount field as described above in which storage columns 7-10 are skipped and 11-15 are set up to represent the digits of the amount, it occasionally happens that the amount consists of five digits which, upon digit setting operations, would occupy all of the storage columns 11-15. Hence, in such instances, there is no opportunity to depress a 0 key 117 one or more times so as to store X representations in certain storage columns. When such a

situation is encountered the operator depresses the five amount keys representing the digits of the amount beginning with the highest denominational order, thence successively to the units digit of the amount. When punching is effected it will be effected in a reverse denominational order, that is, the units digit will occupy column 12, etc., to the highest digit in the tens of thousands order which will occupy column 16. Special provision is made in this situation for setting up an X representation in storage column 10, which is one of the storage columns skipped in digit setting, and this is performed by the depression of the manual bar effected after the last digit of the amount has been set up in storage column 15. From the plugging connection shown in Fig. 9 it will be observed that storage column 10 causes punching at the X index point position of card column 17. Concomitantly with making the X perforation at column 17 the X magnet 182 (Fig. 1) is energized to depress the X skip key to initiate a carriage skipping operation from column 17 to the last column position. The circuit for automatically setting up an X representation in column 10 will now be described.

Upon the depression of the manual bar 118 (Fig. 1a) and with NY4 contacts (Fig. 1j) now transferred it will be observed that a circuit is closed from the line 105, wire 107, through contacts 130, wire 134 (Figs. 1a, 1j), thence through NY4 contacts now transferred, thence through 04 contacts now closed because a digit has been set up in storage column 15, thence through ZE2 contacts now in the position shown, to F2-5 contacts now closed, to energize the punch initiating relay P2. This same impulse is also directed by wire 141 (Fig. 1j, Fig. 1k) through relay contacts R4-1, to the MBR relay. This impulse circuit for MBR relay has been previously described in detail and it will be recalled that when the MBR1 contacts close the R2 relay is energized and held energized to close the R2-1 contacts. The impulse to energize the R2 relay is also directed through the ZE8 contacts (Fig. 1k) now in the position shown, thence through NY8 contacts now closed, through X2 contacts now closed, and through the R2-2 contacts and wire 265 (Figs. 1k, 1b, 1c in order named) to energize the 101 relay of storage column 10, and also through the R2-2 contacts, and wire 266 (Figs. 1k, 1b, 1c in order named) to energize the 104 relay of storage column 10. Such relays are the 1 and 4 code relays of column 10, thus storing up an X representation in storage column 10. Of course, when storage column 10 is read out by the column readout, a perforation will be made at the X index point position of column 17 and will also cause energization of the X magnet 182 (Fig. 1) to initiate carriage skipping operation.

The above provision enables with a shortened amount field the setting up of the digits for the maximum number of columns of the shortened field and automatically, by the operation of the manual bar, enables skipping of the card carriage upon completion of punching of the last digit of the amount.

By use of special key 117X expansion of storage columns for amount digit setting to full capacity when amount of checks exceed five columns—New York form

Provision is made for expanding the digit setting capacity of the storage columns to the maximum number of nine so as to be able to punch nine card columns of the amount field of the

New York form of card when the operator recognizes that the amount of the check exceeds five denominational orders. For five columns or less the shortened amount card field is utilized.

Upon recognizing that the digits of the amount of the check exceed five, the operator realizes that the maximum digit storage capacity of the storage columns is necessary and after depressing the amount key for setting up the storage column 6, which is effected on the sixth key stroke used for setting up the last digit of the ABA number, the operator then depresses the 111X key with the following result. This closes a circuit from the line 105, wire 107 (Fig. 1a), through contacts 124X, to the grounded X relay. The latter closes the X6, or hold contacts, and the stick circuit extends back through such contacts, wire 131, (Fig. 1a) DO2—2 contacts, to line 105. The energized X relay closes the X3 contacts (Fig. 1b) and transfers the X4 contacts (Fig. 1c) and these contacts are held closed and transferred during the setting up of the digits of the amount representing storage columns.

Storage proceeds in the usual manner to columns 1-6. After setting up storage column 6 the next digit storage impulse is then transmitted from CB1 contacts (Fig. 1b), wire 108 (Figs. 1b, 1c), to the C1—4 contacts now closed (Fig. 1c), the F1 contacts now closed, ZE9 contacts now in the position shown, thence through the NY11 contacts now transferred, thence through the X4 contacts now transferred, through the H2 contacts, to the K1—1, K4—1 contacts of storage column 1, to the digit setup relays 11—74 for column 1. The next storage impulse is then transmitted from CB1 contacts, wire 108, through the X3 contacts now closed, wire 109 (Figs. 1b, 1c) to column 8. The X3 contacts still being closed, the next digit impulses then proceed by wire 109 to storage columns 9 and 10. Digit storing proceeds by impulse wire 108 for storage columns 11, 12, 13, 14 and 15 in the usual manner. Of course, after setup of these amounts the manual bar is depressed. In the present example, due to the opening of the X2 contacts (Fig. 1k) it will be seen that impulses cannot be directed to relays 101 and 104 for storage column 10, thereby preventing false X storage in this column.

In the event that the amount of the check consists of nine denominational orders such as, for example, the number \$1,234,876.10, this will be punched in columns 12-20 (Fig. 5) inclusive as 016784321.

Of course, not all of the checks will be of such amounts as to occupy all the nine storage columns and for those higher denominational orders preceding the first significant digit, the 0 key 111 may be depressed so as to store up X representations in the corresponding storage columns. It will be recalled upon setting up of the last storage column of the ABA number or storage column 6, the KB relay is energized to close the KB1 contacts and upon successive zero key depressions for one or more of the higher denominational orders X's will be stored up in the related storage columns. Of course, in punching the card under control of the first of these storage columns read out, a perforation will be made at the X index point position which enables the skipping of the card from the first column which is punched at the X index point position. For example, if the amount of the check is \$1,876.20 this will be set up in storage columns 7-15 in-

clusive as XXX187620. This would be reversely punched as 026781XXX. The X perforation appearing in the column succeeding the column receiving the 1 perforation initiates skipping of the card carriage from such column position.

Signal given to operator when more than 15 key strokes are made—New York form

Since a maximum number of 15 storage columns can be set up when punching according to the New York form, a signal is given to the operator if more than 15 key strokes are made.

When storage column 15 is set up 03 contacts (Fig. 1j) are closed. Upon the sixteenth key stroke circuit is completed from line 105, through COM3 contacts now transferred (Fig. 1a), wire 137 (Fig. 1j), ZE3 contacts, PE2 contacts now closed, NY1 contacts now transferred, C2—11 contacts now closed because of the even numbered key stroke, 03 contacts now closed, to the F2 relay. This causes L3 light (Fig. 1k) to signal the operator indicating the error.

Signal light indicating completion of setting up ABA number—New York form

25 This circuit to light L4 lamp (Fig. 1k) was previously described for the Chicago card form. For the New York card form the circuit extends through F5 contacts and NY9 now transferred. 30 Relay F is energized when column 6 is set up for the last digit of the ABA number. See Fig. 5.

*Zero elimination method—
New York card form*

35 Provision has been made in the machine for a different method of setting up storage columns which not only saves time in punching operations but also in setting up the storage columns, since in this method the storage columns set up correspond in number to the number of digits of the amount. Instead of punching the card columns in reverse denominational order and X skipping over card columns to the right, it is possible to condition the machine for another procedure in 40 which storage of X's is not effected in the storage columns by the 0 digit key depressions. Thus, in setting up the storage columns for an amount of \$5.00, the operator will merely depress three keys in succession for the digits 500 and then 45 depress the manual bar to signify completion of the operation. In this procedure the depression of the manual bar effects an X setting and always in a storage column following the storage column receiving the units digit. This X punched 50 in the column following the units digit column, or in column 15 of the New York form for the amount of \$5.00, can then be used in an accounting machine to control column shifting circuits to shift the 500 to the right a sufficient number 55 of places to bring the units digit of the number into the units order of the accumulator or type bars. In the present punching machine, this X set up in a storage column enables the skipping of the card carriage to a variable number 60 of columns to the last column position depending upon the number of digits set up in the storage columns and perforated; consequently dependent upon the particular storage column receiving the X set up.

65 This method of punching the amounts is described herein as the "zero elimination" method so called because it is unnecessary to depress the 0 key 111 for the storage of X's. When the zero elimination procedure is being used, a plug connection 261 (Fig. 10) is made across plug sockets

268 to energize the ZE relay (Fig. 1e) resulting in the continued energization of this relay and causing the machine to be conditioned for the zero elimination procedure.

When ZE relay is energized the impulse circuits are effective for setting up storage columns 1-10 and, therefore, skipping of storage columns 1-10 which took place in the previously described method is eliminated and such storage columns are set up successively after setting up storage column 6. The transfer of the ZE9 contacts (Fig. 1c) disables the impulse circuit which would be effected through the transferred NY11 contacts and X4 contacts to storage column 10 and permits the impulse to be directed from CB1 contacts (Fig. 1b) wire 108 (Figs. 1b, 1a) to C1-4 (Fig. 1b) F1 contacts, ZE9 contacts now transferred, through H2 contacts, to set up the storage relays 71-74 of column 7. Thus, storage column 7 is set up irrespective of the transfer of the NY11 contacts. For setting up storage columns 8, 9 and 10, it will be observed that the ZE10 contacts (Fig. 1b) now closed allow the digit impulses to be directed from such contacts by wire 109 to columns 8, 9 and 10 in succession.

It is, of course, obvious that the zero digits might be included as one of the digits of the amount of the check when the machine is conditioned for the zero elimination method and to prevent X storage in the storage columns by the depression of the 0 key 117, since the circuits are normally conditioned to effect this operation in setting up digits of the amount field, ZE7 contacts (Fig. 1a) are provided. With the opening of the ZE7 contacts, it will be observed that the impulse transmitted by the depression of the 0 key 117 will not energize the K10 relay. In corresponding storage columns where a zero is to be inserted, none of the relays K1-K4 in that storage column will be energized and only the column relay will be energized to effect a column spacing operation.

Fig. 11 represents the plug connections made when the machine is conditioned for the zero elimination method for the New York card form. It will be observed that the only changes over Fig. 9 is the plug connection 267, and in the manner of making the plug connections between the plug sockets 191 for columns 12-20 of the punch readout and plug sockets 207 for storage columns 7-15. In digit setting, storage columns 7, 8, 9, etc., are set up in succession, the operator depressing the digit keys beginning at the highest denominational order of the amount. By means of the plug connections shown in Fig. 11 the card columns are punched with column 12 receiving the perforation of the digit of the highest denominational order of the amount, column 13 receiving the digit for the next lower order, etc., to higher numbered card columns, depending upon the number of digits in the amount.

After the operator has set up the storage columns for the digits of the amount, the manual bar 118 is then depressed and as a result of this operation an X is stored in the column immediately following the storage column in which the units digit was stored. The circuits closed by the manual bar will not be repeated in detail at this time but it should be recalled that when the manual bar is depressed the MBR and the R1 relays (Fig. 1k) energize to close their MBR1 and R1-1 contacts. Hence, the impulse which is directed to the P2 relay when the manual bar is depressed by the circuit previously described will also be transmitted by wire 141 (Fig. 1k) through

5 the R1 and MBR1 contacts serially, thence through ZE8 contacts now transferred, and wire 270 (Figs. 1k, 1j, 1a in order named) to the K10 relay. The K10 relay will close its K10-1 and K10-2 contacts (Fig. 1a) to energize the K1 and K4 relays in the storage column following the one receiving the units digit. When punching operations are effected, this storage column through its translator will cause the perforation at the X index point position and also cause the energization of the X punch magnet 182 which will initiate a skipping of the card carriage.

10 In order that the sequencing circuits may be properly closed for storage of X representation in the required storage column the MBR2 contacts (Fig. 1a) close and with the ZE6 contacts now closed, it will be observed that a circuit is closed from the line 105, through contacts MBR2, through ZE6 contacts to the COM relay, thence through the COM2 contacts to the CB relay. This closure of COM2 and ZE6 contacts provides the proper circuit closures to energize the alternating relays C1 and C2 as well as by CB1 to enable the impulse to be transmitted to the storage column selected for receiving the X set up.

15 Summarizing, the above arrangement provides, for storage of the digits of the amount of the check and of only those digits which form the amount, the successive punching of such digits beginning at the left hand column and in the same order in which they are stored in the storage columns, the storage of X in a storage column following the one receiving the units digit, and punching of an X in the corresponding card column which provides for a suitable control in the accounting machine for column shifting circuits, and which X storage enables the skipping of the card carriage to skip remaining card columns.

20 *Circuit for effecting energization of P1 relay—Zero elimination method, New York card form*

25 When the machine is conditioned for punching according to the New York card form, without the zero elimination method the energizing circuit for the P1 relay is completed from line 105, COM3 contacts (Fig. 1a), through the NY6 contacts, now transferred, ZE4 contacts at normal, the C2-12 contacts, the M3 contacts, wire 135, PC1 contacts, PD1 contacts, wire 133 to P1 relay. In 30 conditioning the machine for the New York card form using the zero elimination method, the impulse circuit for the P1 relay is directed through the NY6 contacts now transferred, the ZE4 contacts now transferred, and C1-12 and the F3 contacts, both of which are closed. The F relay is energized in setting up storage column 6 so therefore when the seventh key stroke is made which is the key stroke made after the last digit setup of the ABA number of the New York card form, the P1 relay is energized to close P1-3 contacts (Fig. 1a) to initiate card punching operations for punching card columns 1-11 and then stop unless P2 has been energized.

35 *Zero elimination method—Chicago card form*

40 The zero elimination method may also be used for the Chicago card form provided the proper plug connections are made between plug sockets 191 and 207 for punching amount representing card columns according to the direct method. These plug connections are shown in Fig. 10. The digit setup operations are effected just as in the case for the New York form of card using the zero elimination method, except that a maximum of six amount representing storage columns are

set up. However, for setting up the digits of the amount comprising a fewer number of digits, the manual bar is then depressed to thereby store an X in the following storage column. This will be punched on the card in the corresponding card column and the punch carriage will skip from this card column position to the last card column position.

The impulse circuit for column 7 is somewhat different for the Chicago card form when the zero elimination method is used from the New York card form because in this instance the NY11 contacts (Fig. 1c) are now at normal. However, by the transfer of the ZE9 contacts the impulse is directed from wire 108, through C1-4, F1 contacts both closed, ZE9 contacts now transferred, H2 contacts to K1-7 to K4-7 contacts to selectively energize the 71-74 relays. The digit impulses to set up columns 8, 9 and 10 in succession are directed from CB1 contacts (Fig. 1b), wire 108, ZE10 contacts (Fig. 1b), wire 109 (Fig. 1c) to storage columns 8, 9 and 10.

The impulse circuit for P1 for the Chicago card form, zero elimination method, is from line 105, COM3 contacts (Fig. 1a), NY6 contacts now normal, C1-13 and D3 contacts now closed, wire 135, PD1 contacts, wire 133 to P1 relay. When entering the last digit of the ABA number in storage column 4, relay D is energized to close D3 contacts. On making the fifth key stroke C1-13 closes because this is an odd numbered key stroke. This initiates punching of card columns 2-7 and the carriage stops at card column position 8 unless P2 has been energized.

The impulse circuit to energize the P2 relay (Fig. 1j) and also the K10 relay (Fig. 1j) when the manual bar is depressed is somewhat different for the Chicago card form when the zero elimination method is used. With NY4 contacts (Fig. 1j) now at normal the impulse is directed from contacts 130 (Fig. 1a), wire 134 (Fig. 1j), through ZE2 contacts now transferred, F2-5 contacts now closed, to the grounded P2 relay. It will be recalled that this impulse by a circuit previously traced is also directed to cause the K10 relay to be energized for an X storage. Hence, the transfer of the ZE2 contacts enables the energization of the P2 and the K10 relays by the operation of the manual bar after any key stroke made after setting up storage column 4.

Disabling of signal circuits normally operative when operator fails to make an entry in storage column 10 of Chicago card form, or in storage column 15 of New York form

A previous description has been given of the circuits which are operative to give an error indication when the operator fails to make enough key strokes to cause an entry in storage column 10 in the Chicago card form, or column 15 for the New York card form before depression of the manual bar. It will be recalled that for the Chicago card form the impulse to energize the F2 error indicating relay (Fig. 1j) passes through the J4 contacts (Fig. 1j) which are at normal. When the machine is conditioned for the New York card form the circuit passes through the O4 contacts (Fig. 1j) which are at normal. It is evident that since upon the zero elimination method the number of storage columns which are set up is variable such error indication circuits must be rendered inoperative. To this end the ZE1 contacts (Fig. 1j) are inserted in the energizing circuit for the F2 relay. If the operator depresses the manual bar before the J4

contacts are transferred when the zero elimination method is used for the Chicago card form or before O4 contacts are transferred when the zero elimination method is used for the New York card form, the impulse cannot be directed to the F2 relay, due to the opening of the ZE1 contacts.

Special interlock circuit

It will be recalled that the P1 relay (Fig. 1a) 10 is the initiating relay for effecting punching of card columns 2-7 for the Chicago card form and for columns 1-11 of the New York card form and upon completion of punching from the storage columns utilized for such punching the DO1-1 15 relay is energized. The opening of the DO1-1 contacts (Fig. 1c) deenergizes the P1 relay. Thus P1-1 contacts (Fig. 1b) are at normal. At the time that the manual bar is operated PE1 contacts are at normal, because R4-2 (Fig. 1a) 20 opens to deenergize PE, and by closing PE1 closing the impulse circuit to storage column 1 at this point. In series connection with the impulse circuit for storage column 1 are contacts R3-3 (Fig. 1b). In the zero elimination method, it 25 will be recalled that the depression of the manual bar energizes the K10 relay which picks up the K10 and K4 relays to close the corresponding contacts in all storage columns. The manual bar also causes the energization of the R4 relay and the R3 relay which opens the aforesaid R3-3 contacts. Therefore, when the manual bar is depressed R3-3 contacts open the impulse circuit to storage column 1, although the other contacts in the impulse circuit for storage column 30 1 may be closed, preventing false setup in storage column 1 on a manual bar depression following the deenergization of the P1 relay.

Disabling error indication when operator makes too many key strokes before depression of the manual bar

There was previously described the circuits for 35 energizing the error indication relay F2 (Fig. 1j) in the event that the operator makes too many 40 key strokes before the manual bar depression. This error indication was supplied because when 45 punching the card according to the New York card form and the Chicago card form, a predetermined number of card columns should be set up. It will be recalled the energizing circuit for the F2 relay passes through the ZE3 contacts (Fig. 1j). In the zero elimination method the 50 ZE3 contacts are open to prevent this signal circuit from being operative.

Column indicating signal lights

While the lamp L1 (Fig. 1k) has been provided to indicate that a setup has been completed as far as storage column 4 when punching according 60 to the Chicago card form, and also by the shift of the NY9 contacts when setup has been completed to storage column 6 according to the New York card form, it is desirable to provide signal lights to indicate the storage columns that have 65 already been set up if a complete setup has not been made. To this end for each of the storage columns 1-6 inclusive related signal lights 280 are provided and visible to the operator, as shown in Fig. 12. For energizing each signal light the 70 storage relays 1-4 of the related storage column have supplemental "7" contacts (Fig. 1e) which are closed when one or more relays are energized for the entry of a significant digit 1-9. For example, in storage column 1 the relays 11, 12, 13 and 75 14 close contacts 11-7, 12-7, 13-7 and

14—7, the same taking place for the other storage columns. If the storage column represents "0" the lamp will not be lighted. The lamps 272 for storage columns 1 and 2 are connected to the ground through a switch S1 and lamps for storage columns 5 and 6 are connected to the ground through switch S2, whereas the lamps for storage columns 3 and 4 have a permanent wire connection to the ground.

It will be also observed that one side of each of the "7" contacts for each storage column has a wire connection to the related lamp whereas the other side of the contacts closed by the storage relays of a storage column are commonly connected to a wire 273. It is desirable that the supplemental signal lights 272 be illuminated only where an error indication has been made, reflected by the energization of the F2 relay under the different circumstances noted. In the present embodiment wire 273 (Figs. 1e, 1d, 1c, 1b, 1k in order named) is connected to the line 105 through the F2—4 contacts (Fig. 1k). Hence, the closure of the latter will energize one or more signal lights 272. As an error that could be made it should be understood that it is quite possible for the operator to erroneously depress the manual bar before completion of setting up of the storage columns 1—6 for the New York card form, and 1—4 for the Chicago card form and in each instance if this is done in error the F2 relay will energize to close the F2—4 contacts and light the lamps. Operation of the error key 117E extinguishes the lamps by energizing DO1 relay to open DO1—1 contacts (Fig. 1c) to deenergize F2 relay.

Switches S1 and S2 are both closed so that the signal lights 272 are in circuit connection when the machine is conditioned for the New York card form since these storage columns are set up for the State number and the ABA number. Switch S2 is not closed for the Chicago card form because only storage columns are set up for the ABA number.

When an error occurs those columns which contain a significant digit will cause their respective lamps to light and those containing a zero will remain "out." The operator can then tell if the error is one of position, should the bank number contain one or more zeros, or if one or more lights remain "out" when the bank number contains no zeros.

While there have been shown and described and pointed out the fundamental novel features of the invention as applied to a single modification, it will be understood that various omissions and substitutions and changes in the form and details of the device illustrated and in its operation may be made by those skilled in the art without departing from the spirit of the invention. It is the intention therefore to be limited only as indicated by the scope of the following claims.

What is claimed is:

1. In a machine of the class described, the combination of a punching machine including a step by step movable card carriage and punch operating elements, a multiple column keyboard and contact digit representing means set thereby, a plurality of columns of storage relays, ten key keyboard controlled means for energizing said columns of storage relays in succession, means to hold said energized relays in an energized status, column readout means operable by said carriage and including selective connections between said readout means and said storage columns and be-

5 tween said readout means and said multiple column keyboard for variably determining the card columns punched under control thereof, means operable upon completion of the setting up of the columns of storage relays to effect the operation of said readout means to cause the successive operation of said punch operating elements under control of said keyboard contact digit representing means and said energized storage relays, and means operable by said card carriage to disable the means to hold the energized relays in an energized status to restore said relays to a deenergized status.

2. In a machine of the class described, the combination of a punching machine including a step by step card carriage and punch operating elements, a multiple column keyboard and contact digit representing means set thereby to effect digit representation according to the Hollerith code, a plurality of columns of storage relays, ten key keyboard means for energizing said columns of storage relays in succession and in a combinational code, means to hold said energized relays in an energized status, translating means for each column of storage relays to convert the combinational code setting to a Hollerith code of digit representation, column readout means operable by said card carriage and including selective connections between the readout means and the translating means of said storage columns and between the readout means and the contact digit representing means of said multiple column keyboard for variably determining the card columns punched under control thereof, means operable 30 upon completion of the setting up of the columns of storage relays to effect the operation of said readout means to cause the successive operation of said punch operating elements under control of said keyboard contact digit representing means and said translating means to punch successive card columns according to the Hollerith code, and means operable by said card carriage to disable the means to hold the energized relays in an energized status to restore said relays to a deenergized status.

3. In a machine of the class described, the combination of a punching machine including a step by step card carriage and punch operating elements, a multiple column keyboard and contact digit representing means set thereby, a plurality of sets of storage columns each comprising a plurality of columns of storage relays, ten key keyboard means for energizing said columns of storage relays in succession, means to hold said energized relays in an energized status, column readout operable by said carriage and including selective connections between said readout means and sets of storage columns and between said readout means and said multiple column keyboard for variably determining the card columns punched under control thereof, means operable upon completion of the setting up of one of the columns of storage relays in the second set to effect the operation of said readout means to cause the successive operation of said punch operating elements under control of said keyboard contact digit representing means and said energized storage relays of the first named set, means operable upon completion of the setting of the last storage column set up in the second set to cause the operation of the readout means to effect the operation of the punch operating elements under control of said second set of storage columns, and means operable by said card carriage when at different card col-

umn positions to disable the means to hold the energized relays of each of said sets in an energized status to restore said relays to a deenergized status upon completion of punching under control of such relays.

4. In a machine of the class described, the combination of a punching machine including a step by step card carriage and punch operating elements, a plurality of sets of columns of storage relays, each set comprising a plurality of columns of storage relays, ten key keyboard means for energizing said columns of storage relays in succession, a plurality of means, one for each set of relays to hold said energized relays of the related set in an energized status, column readout means operable by said card carriage and including selective connections for variably determining the card columns punched under control of the said sets of storage relays, means operable upon completion of the setting up of the columns of storage relays in each of said sets to effect the operation of said readout means to cause the successive operation of said punch operating elements under control of said energized storage relays of the related set, and means comprising selective connections between said readout means and said plurality of means to selectively operate said means to restore said relays to a deenergized status at different card column positions of said carriage and when punching has been effected under control of the related set of energized relays.

5. In a machine of the class described, the combination of a punching machine of the successive punch operation type and including punch control elements, a plurality of sets of storage devices, each set comprising a plurality of columns of storage devices corresponding to the number of columns of a card field to be punched, keyboard controlled means for setting up said column of storage devices in succession to represent digits of two amounts, means to operate said control elements under control of each of said sets of storage devices, and means responsive to the setting up of the digits in a predetermined column of storage devices of the second set to cause the operation of said punch control elements under control of the first column of the first set of storage devices set up and thereby initiate the operation of the punching machine to punch the first card field under control of the first set of storage devices.

6. In a machine of the class described, the combination of a punching machine of the successive punch operation type and including punch control elements, a plurality of sets of storage devices, each set comprising a plurality of columns of storage devices corresponding to the number of columns of a card field to be punched, keyboard controlled means for setting up said columns of storage devices in succession to represent digits of two amounts, means to operate said control elements under control of each of said sets of storage devices, and means responsive to the setting up of the digits in a predetermined column of storage devices of the second set to cause the initiation of the said last named means to cause the operation of said punch control elements under control of the first set of storage devices.

7. In a machine of the class described, the combination of a punching machine of the successive punch operation type and including punch control elements, a plurality of sets of storage devices, each set comprising a plurality of col-

umns of storage devices corresponding to the number of columns of a card field to be punched, keyboard controlled means for setting up said column of storage devices in succession to represent digits, means to operate said control elements under control of each of said sets of storage devices, means responsive to the setting up of the digits in a predetermined column of storage devices of the second set to cause the initiation of the said last named means to cause the operation of said punch control elements under control of the first set of storage devices, and manually operated means to cause the operation of said last named means to cause the operation of said punch control elements under control of the second set of storage devices when the last column thereof has been set up.

8. In a machine of the class described, the combination of a punching machine of the successive punch operation type and including punch control elements, a plurality of sets of storage devices, each set comprising a plurality of columns of storage devices corresponding to the number of columns of a card field to be punched, keyboard controlled means for setting up said column of storage devices in succession to represent digits, means to operate said control elements under control of each of said sets of storage devices in succession, means responsive to the setting up of the digits in a predetermined column of storage devices of the second set to cause the initiation of the operation of said punching machine by causing the successive operation of said punch control elements under control of the first set of storage devices and then stop when all storage columns thereof have controlled said punch control elements, and manually operated means operated after all storage columns of the second set have been set up to effect the second initiation in operation of the punching machine by causing the successive operation of said punch control elements under control of said second set of storage devices.

9. In a punching machine of the successively operated punch type wherein punching of card columns is effected in succession both from a multiple column keyboard and one or more columns of digit storage devices, the combination of the aforesaid columns of digit storage devices and said multiple keyboard, contact devices operable by said multiple keyboard to represent digits, means to set up said columns of digit storage devices in succession to represent digits of an amount, punch operating elements of said punching machine, means for reading out said storage columns in succession and said contact devices of said keyboard in succession to effect the operation of the punch operating elements to punch card digit representing columns of two fields in succession, a relay operable by said reading out means when at a position corresponding to the card column for receiving dual perforations, and means operable by said relay to cause a storage column and contact devices of one order of the keyboard to jointly and concurrently select punch operating elements to dually punch a single card column to represent the digits set up on the controlling storage column and contact devices.

10. In a punching machine of the class described in which punching is effected column by column, the combination of a keyboard and setup means controlled thereby, a plurality of columns of storage devices, there being one column of storage devices for each card column punched, se-

- quencing means controlled by said keyboard for setting up through said setup means said storage columns in succession to represent digits, and means for controlling said setup means to cause a digit setup effected after a predetermined number of keyboard operations to be diverted to a storage column non-adjacent to the preceding storage column setup, whereby intermediate storage columns are omitted in the digit setup.
11. In a punching machine of the class described in which punching is effected column by column, the combination of punch operating elements of said punching machine, a keyboard and setup means controlled thereby, a plurality of columns of storage devices, there being one column of storage devices for each card column punched, sequencing means controlled by said keyboard for setting up through said setup means said storage columns in succession to represent digits in all storage columns, means for controlling said setup means to cause a digit setup effected after a predetermined number of keyboard operations to be diverted to a storage column non-adjacent to the preceding storage column setup, whereby intermediate storage columns are omitted in the digit setup, and means for reading out said storage columns in the order reverse to the denominational order they are set up to operate said punch operating elements to punch card columns beginning at the left hand card column of a card field and for as many card columns as storage columns are set up to represent digits.
12. In a punching machine of the class described in which punching is effected column by column, the combination of punch operating elements of said punching machine, a keyboard and setup means controlled thereby, a plurality of columns of storage devices, there being one column of storage devices for each card column punched, sequencing means controlled by said keyboard for setting up through said setup means said storage columns in succession to represent digits, means for controlling said setup means to cause a digit setup effected after a predetermined number of keyboard operations to be diverted to a storage column non-adjacent to the preceding storage column setup, whereby intermediate storage columns are omitted in the digit setup, and means for successively reading out said storage columns to effect the operations of the punch operating elements to punch card columns corresponding to the storage columns set up to represent digits.
13. In a card punching machine of the class described which includes punch operating elements, the combination of a keyboard, a plurality of columns of storage devices, there being one column of storage devices for each card column punched, setup means controlled by said keyboard for setting up said storage columns to represent digits, means for controlling said setup means to cause a digit setup effected after a predetermined number of keyboard operations to be diverted to a storage column non-adjacent to the preceding storage column setup, whereby intermediate storage columns are omitted in the digit setup, and means for reading out said storage columns in succession to operate said punch operating elements to punch card columns in succession and for a number of card columns corresponding to the number of storage columns set up to represent digits.
14. In a card punching machine of the class described, the combination of a keyboard, a plu-
- 5 10 15 20 25 30 35 40 45 50 55 60 65 70 75
- rality of columns of storage devices, there being one column of storage devices for each card column punched, setup means controlled by said keyboard for setting up said storage columns to represent digits, and means for controlling said setup means to cause a digit setup effected upon a predetermined keyboard operation to be diverted to a storage column non-adjacent to the preceding storage column setup, whereby intermediate storage columns are omitted in the digit setup.
15. In a machine of the class described, the combination of a punching machine of the successive punch operation type including a skipping mechanism for the card carriage thereof and punch control instrumentalities, a plurality of columns of storage devices, keyboard controlled means for setting up said storage devices to represents digits and for setting up one or more columns of storage columns not receiving digits of an amount to represent a special designation, means for successively reading out said columns of storage devices to control said punch control instrumentalities to punch successive card columns, and means for causing said skipping mechanism to be operative upon reading out one of the columns of storage devices representing the special designation.
16. In a machine of the class described, the combination of a punching machine of the successive punch operation type including a skipping mechanism for the card carriage thereof and punch control instrumentalities, a plurality of columns of storage devices, keyboard controlled means for setting up said storage devices to represent digits 0-9 and under control of the 0 key for setting up one or more columns of storage columns preceding those receiving digits of an amount to represent a special designation, means for successively reading out said columns of storage devices to control said punch control instrumentalities to punch digits in successive card columns, and means for causing said skipping mechanism to be operative upon reading out one of the columns of storage devices representing the special designation.
17. In a machine of the class described, the combination of a punching machine of the successive punch operation type including a skipping mechanism for the card carriage thereof and punch control instrumentalities, a plurality of columns of storage devices, keyboard controlled means comprising digit keys 1-9 for setting up said storage devices to represent digits and under control of the 0 key for setting up one or more columns of storage columns preceding those receiving digits of an amount to represent a special designation, means for successively reading out said columns of storage devices in an order reverse to the order the columns are set up to control said punch control instrumentalities to punch successive card columns, and means for causing said skipping mechanism to be operative upon reading out the first column of storage devices representing the special designation.
18. In a machine of the class described, the combination of a punching machine of the successive punch operation type including a skipping mechanism for the card carriage thereof and digit and special designation punch control instrumentalities, a plurality of columns of storage devices, keyboard controlled means for setting up said storage devices to represent digits and for setting up one or more columns of stor-

age columns not receiving digits of an amount to represent a special designation, means for successively reading out said columns of storage devices to control said digit punch control instrumentalities to punch successive card columns to represent digits of the amount and means for causing said skipping mechanism to be operative upon reading out the first column of storage devices representing the special designation and for causing the operation of a punch control instrumentalities to represent the special designation by a perforation in a card column following the card column receiving the last digit of the amount.

19. In a machine of the class described, the combination of a punching machine of the successive punch operation type including a skipping mechanism for the card carriage thereof and digit punch control instrumentalities, a plurality of columns of storage devices, keyboard controlled means comprising keys for setting up said storage devices to represent digits and for setting up one or more columns of storage columns not receiving digits of an amount to represent a special designation, means for successively reading out said columns of storage devices to control said punch control instrumentalities and including means connecting said storage devices and said punch control instrumentalities to punch successive card columns beginning at the left of a card field, and means for causing said skipping mechanism to be operative upon reading out the first column of storage devices representing the special designation to skip higher numbered card columns of the same field.

20. In a machine of the class described, the combination of a punching machine of the successive punch operation type and including a card carriage, a set of punch control elements and a carriage skipping mechanism, a plurality of columns of storage devices set up to represent digits and a special carriage skipping control designation, means comprising keys for setting up said columns of storage devices in a predetermined denominational order and for setting up one or more initial columns of storage devices to represent said control designation, means operable by said carriage for reading out said storage columns in succession for operating said digit punch control elements under control of said storage devices according to their digit representations and including selective connections between said storage columns and column representing elements of said reading out means to effect punching of a selected field of the card and successively in columns of a selected field in an order reverse to the denominational order said columns of storage devices are set up, whereby the last column of the initial columns of storage devices set up to represent said control designation is the first one read out to cause the operation of said carriage skipping mechanism, and means to cause the column of storage devices representing the carriage skipping control designation and read-out to operate said carriage skipping mechanism.

21. In a machine of the class described, the combination of a punching machine of the successive punch operation type and including a card carriage, a set of punch control elements and a carriage skipping mechanism, a plurality of columns of storage devices set up to represent digits and a special carriage skipping control designation, means comprising keys for setting up said columns of storage devices in a pre-

determined denominational order and for setting up one or more columns of storage devices to represent said control designation, means operable by said carriage for reading out said storage columns in succession for operating said digit punch control elements under control of the storage devices according to their digit representations to effect punching successively in columns of a field in an order reverse to the denominational order said columns of storage devices are set up, whereby the last column of storage devices set up to represent said control designation is the first one read out to cause the operation of said carriage skipping mechanism, and means to cause the column of storage devices representing the carriage skipping control designation and readout to operate said carriage skipping mechanism.

22. In a machine of the class described, the combination of a punching machine of the successive punching type and including a card carriage, a set of punch control elements and a carriage skipping mechanism, a plurality of columns of storage devices set up to represent digits and a special carriage skipping control designation, means comprising keys for setting up said columns of storage devices in a predetermined denominational order and for setting up at least one column of storage devices to represent said control designation, means operable by said carriage for reading out said storage columns in succession for operating said digit punch control elements under control of said storage devices according to their digit representations and including selective connections between said storage columns and column representing elements of said reading out means to effect punching of a selected field of the card and successively in columns of a selected field, whereby the column of storage devices set up to represent said control designation is read out to cause the operation of said carriage skipping mechanism, and means to cause the column of storage devices representing the carriage skipping control designation to operate said carriage skipping mechanism.

23. In a machine of the class described, the combination of a punching machine of the successive punch operation type and which includes punch control elements and a card carriage skipping mechanism, a plurality of columns of storage devices set up to represent digits of an amount and a special carriage skipping control designation, key controlled means comprising digit keys 0-9 for setting up digit representations in said columns of storage devices in succession and including means under control of the 0 digit key for setting up one or more columns of storage devices preceding those receiving digit setups of the amount to represent the carriage skipping control designation, means responsive to the operation of the first digit key 1-9 to render said 0 key ineffective to set up any subsequent column of storage devices to represent said carriage skipping control designation when said 0 digit key is operated for setting up zeros pertaining to the amount, means for successively reading out said columns of storage devices in succession to operate said punch control elements to punch successive card columns, and means for causing said skipping mechanism to be operative after punching the card columns and upon reading out one of the columns of storage devices representing the carriage skipping control designation.

24. A machine according to the preceding

claim 23 in which a supplemental plurality of storage columns are provided for punching a preceding card field, and said storage columns may be varied in number to punch a predetermined number of card columns, characterized by the provision of a plurality of devices selectively operable when digit setting is effected for the last of the predetermined number of storage columns set up, and means controlled by each of said devices when operable to render the means under control of the 0 key for setting up a column of storage devices to represent the control designation effective when the first column of storage devices for the next card field is set up.

25. In a machine of the class described, the combination of a punching machine of the successive punch operation type including a skipping mechanism for the card carriage thereof, and punch control elements, a plurality of columns of digit storage devices for representing digits of an amount or a carriage skipping control designation and a supplemental storage column for representing a carriage skipping control designation, keyboard controlled means for setting up said digit storage devices to represent digits, and for setting up one or more of said digit storage devices to represent said control designation when all of said digit storage devices are not set up to represent an amount, means for reading out said digit storage devices in succession to operate the selected punch control elements to punch card columns successively to represent the amount and one of said digit storage devices or the supplemental storage column to operate said carriage skipping mechanism when one of said storage devices is set up to represent said control designation, means for initiating the operation of said last named means when all of said storage columns are set up, and means controlled by said initiating means to set up said supplemental storage column to represent said control designation when all of said digit storage devices are utilized to represent digits of an amount.

26. A machine according to the preceding claim 25 which the 0 digit key of said keyboard controlled means causes the operation of the setting up means for the digit storage columns to represent said control designation prior to the operation of the digit keys 1-9 to set up said digit storage columns to represent digits of the amount, and provided with means responsive to the operation of any digit key 1-9 for disabling said last named setting means to enable subsequent operation of the 0 digit key to set up digit storage columns to represent zeros of the amount of lower denominational orders.

27. In a machine of the class described, the combination of a punching machine of the successive punch operation type including a skipping mechanism for the card carriage thereof, and punch control elements, a plurality of columns of digit storage devices for representing digits of an amount or a carriage skipping control designation and a supplemental storage column for representing a carriage skipping control designation, keyboard controlled means for setting up said storage devices to represent digits, and for setting up one or more of said storage devices to represent said control designation when all of said digit storage devices are not set up to represent an amount, means for reading out said digit storage devices in succession and in reverse to the order they are set up to operate the selected punch control elements to punch

card columns successively in reverse denominational order to represent the amount in such reverse order, and one of said digit storage devices or the supplemental storage column after card columns have been punched to represent the amount to operate said carriage skipping mechanism when one of said storage devices is set up to represent said control designation, means for initiating the operation of said last named means when all of said digit storage columns are set up, and means controlled by said initiating means to set up said supplemental storage column to represent said control designation when all of said digit storage devices are utilized to represent digits of an amount.

28. In a punching machine of the successively operated punch type which includes punch selecting elements and a card carriage skipping mechanism, a plurality of columns of storage devices set to represent digits of an amount, and at least one of said storage columns set to represent a carriage skip control designation, means for initiating the operation of said punch selecting elements under control of the column of storage devices set, and for causing the operation of the carriage skipping mechanism under control of the storage column set to represent said carriage skip control designation, and means controlled by said initiating means to set one of said columns of storage devices to represent said carriage skip control designation.

29. In a punching machine of the successively operated punch type which includes punch selecting elements and a card carriage skipping mechanism, a plurality of columns of storage devices successively set to represent digits of an amount, and one of said storage columns set to represent a carriage skip control designation, means for effecting the operation of said punch selecting elements under control of the column of the setup storage devices to punch digits of an amount in the order they are set up on said storage columns, and for causing the operation of the carriage skipping mechanism under control of the storage column set to represent said carriage skip control designation, punch initiating means to set said last named means in operation, and means controlled by said initiating means to set one of said columns of storage devices comprising the storage column following the storage column representing the units digit of the amount to represent said carriage skip control designation.

30. In a punching machine of the successively operated punch type which includes punch selecting elements and a card carriage skipping mechanism, a plurality of columns of storage devices set to represent digits of an amount, and one of said storage columns set to represent a carriage skip control designation, key controlled means including sequencing means to set said storage columns in succession from the highest denominational order to the units denominational order, means for effecting the operation of said punch selecting elements under control of the column of storage devices set to punch card columns in the order the digits are set up, and for causing the operation of the carriage skipping mechanism under control of the storage column set to represent said carriage skip control designation, punch initiating means to set said last named means into operation and means controlled by said initiating means to operate said sequencing means to set the storage column following the storage column represent-

ing the units digit to represent said carriage skip control designation.

31. In a punching machine of the successively operated punch type which includes punch selecting elements and a card carriage skipping mechanism, a plurality of columns of storage devices set to represent digits of an amount, and at least one of said storage columns set to represent a carriage skip control designation, means for effecting the operation of said punch selecting elements under control of the column of storage devices set to punch the digits of the amount in the order they are set up in the storage columns, and for causing the operation of the carriage skipping mechanism under control of the storage column set to represent said carriage skip control designation and under control of such storage column the punching of a hole in a card column following the one representing the units digit of the amount, whereby said hole may be utilized in an accounting or printing machine to effect denominational shift of the perforated amount, punch initiating means to effect the operation of said last named means, and means controlled by said initiating means to set one of said columns of storage devices to represent said carriage skip control designation.

32. In a punching machine of the successively operated punch type which includes punch selecting elements and a card carriage skipping mechanism, a plurality of columns of storage devices set to represent digits of an amount, and at least one of said storage columns set to represent a carriage skip control designation, means for effecting the operation of said punch selecting elements under control of the column of storage devices set to punch digits of an amount beginning at the left hand column of a field, and for causing the operation of the carriage skipping mechanism under control of the storage column set to represent said carriage skip control designation to skip columns of the field to the right of the units digit column, means for effecting the operation of said last named means, and means controlled by said initiating means to set the column of storage devices following the one set to represent the units digit to represent said carriage skip control designation.

33. In a machine of the class described, the combination of a punching machine of the successive punch type and including a card carriage and a set of digit punching instrumentalities, a plurality of columns of storage devices set to

represent digits, reading out means operable by said carriage for reading out said storage columns in succession and for operating said digit punch instrumentalities according to the digit representations and including selective connections between said storage columns and column representing elements of said reading out means arranged to effect punching in an order reverse to the denominational order said columns of storage devices are set up, and means comprising

keys for setting up said columns of storage devices in a predetermined denominational order.

34. In a machine of the class described, the combination of a punching machine of the successive punch type and including a card carriage and a set of digit punching instrumentalities, a plurality of columns of storage devices set to represent digits, means operable by said carriage for reading out said storage columns in succession and for operating said digit punch instrumentalities according to the digit representations and including selective connections between said storage columns and column representing elements of said reading out means arranged to effect punching of a selected field of the card and successively in columns of a selected field in an order reverse to the denominational order said columns of storage devices are set up, and means comprising keys for setting up said columns of storage devices in a predetermined denominational order.

35. In a machine of the class described, the combination of a punching machine of the successive punch type and including a card carriage and a set of digit punching instrumentalities, a plurality of columns of storage devices set to represent digits, means comprising a brush operable by said carriage over contact elements spaced according to the card columns for reading out said storage columns in succession and for operating said digit punch instrumentalities according to the digit representations and including selective connections between said storage columns and selected contact elements of said reading out means to effect punching of a selected field of the card and successively in columns of a selected field in an order reverse to the denominational order said columns of storage devices are set up, and means comprising keys for setting up said columns of storage devices in a predetermined denominational order.
